[57] ABSTRACT

A visual and audible passing and lane changing signalling system for automobiles, including a steering wheel having opposite switches thereon for left and right hand signalling; a rotary electrical connector joining conductors from the wheel through the steering wheel shaft and method for making same; and the visual and audible signalling means.

VIDEO AND AUDIO PASSING AND LANE CHANGING SIGNALING SYSTEM FOR VEHICLES

This application is a continuation of my similarly entitled pending application Ser. No. 501,405, now abandoned, which was filed Oct. 22, 1965.

BRIEF SUMMARY OF THE INVENTION

The system includes a rotatable electrical connector supported on the steering wheel and the steering column, one mating part on each. Each part consists of coaxial, insulated cylindrical contacts connected to leads, with the contacts of each part abutting. Spring means biases the contacts of one part toward the other.

Considering all the God fearing and loving aspects of self-preservation, this invention sets forth the novel means of a video and audio passing signal system thru the medium of electronics and from any preselected, stationary and desired switch positions on the spokes of an automobile steering wheel and/or on the outer perimeter rim of a steering wheel.

Henceforth, simple, quick and explicit passing and lane changing communications between operators of vehicles shall be activated by a single unit type multiple switch of which a unit will be located to suit on the right and left sides of a steering wheel, for which rudimentary confusion will be entirely eliminated in regard to the left or right passing or lane changing intentions.

Assuming that egg crate dividers will partition and divide the presently used tail lights and front parking lights into separate units for which one division will be reserved for a green light; the passing signal system will resemble the presently used directional signal system, since a special and respective colored light will illuminate the left or right sides (front and rear) of a vehicle for its specific intention.

Since the present turn signal or directional signal mechanism utilizes a large percentage of the available space in the lower hub of a steering unit, any new type device that is used in conjunction with and as a companion feature, makes space and its locations a prime and important feature.

Since the quick access to turn signals is of no consequence and now that the public is acquainted with its lever intention and activation, the present turn signal mechanism should be retained and lowered approximately one half inch in the secondary lower steering column. Thereafter, the lower half slip ring assembly, which is a novel means of transferring electricity to a revolving steering wheel by any desired number of wires, can be positioned on top of the presently used turn signal mechanism and in a matching and mating relationship to the upper slip ring assembly which is housed, located and positioned in the counterbored portions of a conventionally used steering wheel.

Now that electricity has been transferred up and thru the steering column, the lead and return wires will enter a novel means of a steering wheel construction by a conduit system and its special fittings and casting to which will resemble a plumbing system. The usual solid type construction will be absent where a switch is desired and positioned but the solid rod will make up the remainder of the steering wheel by welded segments. By this method of construction, and since every individual has a personal and different selective reason for positioning their hands on a steering wheel, the switches will be positioned to suit each operator so that quick and feasible switch activations can be obtained

for lane changing and passing intentions without removing their hands from the steering wheel.

Concerning the outer steering wheel rim perimeter and from any preselected quadrant and its opposite quadrant also, a multiple switch will be installed inside of a special switch box casting or a structural segment type casting or a plumbing type fitting with a rectangular opening in the top portion. After assembly, a main horizontal activation type switch button will be positioned on the top portion of the steering wheel whereby no extrusion will change the continuity of the normal profile. In the center of this main switch button and projecting upward from the top portion of this main switch button there will be another small passing horn button which will have vertical activation. In conjunction with this horn button and from the underside of the steering wheel a rather large segment of grip knobs will constitute a volume horn selector button, which by a 0.050 thousandth or a small horizontal activation will select an extra loud volume (a country volume or a city volume) for its special passing sound when the passing horn button is depressed.

Considering the two independent but related video aspects of this invention which are produced from sliding the main switch button to the left of center or the off position or the right of center or the off position, we establish a solid green hold light and a blinking passing light which will be projected from a double filament bulb on its respective and selected sides of a vehicle.

Prior to passing or lane changing intentions the hold light will give advance notice of an operators intentions and the blinking passing light is almost self-explanatory; but, the inventors intent and pertinent values will later be described.

Knowing the wide range of the operators mentality, the inventor engineered this patent to be simple, effective and foolproof from the viewpoint of operational errors as long as an operator knows his right hand from his left hand. This is the reason for installing switches on the left side of the steering wheel for left hand intentions and switches on the right hand side of the steering wheel for right hand intentions.

When considering the possibility of errors in selecting a hold light or a blinking passing light and concerning the switches on the left side of the steering wheel, the blinking passing light will be illuminated when the main switch button is horizontally slid in the direction that the operator wishes to pass. The same condition pertains to the switches on the right side of the steering wheel inasmuch as the main switch is horizontally slid in the direction that the operator wishes to pass or change lanes. Obviously the hold lights will always be illuminated by sliding the main switch in the opposite direction or to the opposite side of the center or the off position. This simple condition is the only condition that an operator needs to remember.

To eliminate rudimentary errors and to aid and doublecheck the operators selection of the blinking passing light and from the extreme left and right sides of the instrument panel, a blinking green dash light with an intermittent bell sound will give a video and audio confirmation.

To aid and doublecheck the operators selection of the hold light and from the extreme left and right sides of the instrument panel, a solid green light will be projected.

Now we will consider malfunctions and possible errors in selecting a hold light or the blinking passing light or the presently used directional signal system and in view of the few errors that may be made, these errors are much better than no type of signal because alert operators will be able to detect an error and make allowances for this condition.

To understand the most vague type of a signaling system between operators, we will use the condition of driving after dark. When we meet an approaching vehicle, most people dim their lights by manual function. When this mutual courtesy is accomplished in a quick manner we are premonitorily and partially assured that the driver isn't intoxicated or asleep; and, there is a momentary transition of safety exchange between these drivers even though an accurate visual perception is not possible.

When the presently used turn signals are left on and the operators vehicle is in the incorrect lane of a multiple laned road (or street) for the indicated turn, the unsafe drivers are quickly noticed; but, still these lights help correct and guide all the concerned operators even though their thoughts shall not be worthy of publication. It is the quick and erratic actions that are potential killers to which gives no indications or warnings.

Many people now use their directional signals for passing signals and with a degree of safety intent but each intersection and turn off creates a doubt as to whether they wish to turn, pass or change lanes. Quick and accessible switch activation is not possible and further restricted by and thru the self-cancelling cam means when the steering wheel is in several of its different rotatable positions.

In time, all operators of this new system will select and slide the main switch buttons in a similarity that a typist selects the different letters of the alphabet. There are forty eight keys on a typewriter. Most typists cannot name these keys in their respective sequence but still can select and push these keys with incredible and unbelievable speeds. Then surely the public can then slide a single switch button when their thumbs are already on these buttons for left or right hand passing intention.

As previously stated, there will be a passing horn button in the middle of the main switch which will require vertical action for its activation. Since there is a passing horn button on the left side of the steering wheel and on the right side of the steering wheel, we then establish a special high pitched sound which will designate that a vehicle is passing on the left side. When a special low pitched sound is heard, the operator has depressed the horn button on the right side of the steering wheel which designates that the vehicle will or is passing on the right side.

As previously expressed, a volume selector button will preselect or instantaneously change the volume from extra loud to either a soft or medium tone of the same pitch and from either side of the steering wheel.

The tone should be standardized for universal and explicit intent and the tones will not be harmonious as our twin and conventional used horns are; but, each high and low pitch will have a definite meaning and affect.

While operating a vehicle in a strange city there are occasions when a good driver might wander too close to another zoned lane and the usage of conventional horns often causes more confusion and sometimes makes matters worse. Passing horns will notify the operator of the vehicle to be passed as to which way to

turn to avoid an accident without taking precious time to observe the whole situation.

Since the usage of these passing horns may be an optional condition to suit any existing condition the passing horn button on either side of the steering wheel may be used at any time when the main button is in a middle or off position, left hold light (and this condition may be reversed since it depends upon which switch we are talking about) or right blinking light position.

10 The inventor is conscious of the fact that any appreciable change in steering wheel construction or seating arrangements may change the accustomed positioning of the operators grip even if it is the same individual.

15 Henceforth, the construction choice and versatility in positioning switches is an important factor in view of accessibility and functional ease. With this thought in mind, custom made steering wheels may be installed on all new and used vehicles with a universal standardization or in conjunction with the presently used turn signals or, without changing the original design, etc. Any desired change in switch arrangements can be obtained by pulling the original steering wheel and by replacing it with a custom made unit whether it has or has not passing signal switches.

20 25 In view of state legislation for national standardization the inventor desires to express the true values of this passing signal system by repetitious, typical and daily examples and/or events.

30 On many occasions innocent people become the tragic victims of various passing conditions which are partially caused by being too bold or too timid and in the absence of any feasible means of consistency in regard to personal and universal passing habits.

35 Using the condition of a two laned road of which one lane goes each way and when one, two or many cars catch up with a slower moving vehicle, the first car behind the slow moving vehicle has the right to pass. To establish this priority right by a video system the operator will immediately illuminate the hold light with his left hand. Since the second car may want the same passing rights in turn, they also will illuminate their hold light. Then when the proper passing condition is obtained the operator of the first car will slide the main switch button in the direction that they wish to pass and to its extremity which will cancel out the hold light for the blinking passing light intention. From deliberation and confusion we operators do not know who wants to pass and who should pass. Precious and crucial passing time is lost.

40 45 50 If the first car behind the slow moving vehicle does not wish to pass they should allow a passing space between these now two slow moving vehicles. By not using their hold light they give up their priority passing rights whereby the next vehicle with an illuminated hold light will obtain this passing priority.

55 60 65 Heretofore and perhaps only one time out of a hundred almost everyone is guilty of momentary insanity which instigates various forms of inconsistent passing methods of which it later makes the most intelligent people wonder about their judgement and intelligence. Henceforth, the hold light will become the rule of the road whereby everyone must and will reconcile themselves to taking their appropriate turns for a personalized and a standardized universal passing habit.

When universal reconciliation is established one does not mind waiting since the mind can only think of one thing or thought at a time; and, if there is a standard-

ized system this thought trend will become automatic whereby anxiety and impatience are not stimulated by erratic thoughts.

When we go to a movie and there is a line of people waiting to get their tickets, we do not go ahead of the line like a bunch of pigs. We customarily observe the length of the line and take our turn at the end of the line or abstain from participation. Such may be the case in regard to passing rights only with more life and death emphasis.

The present traffic light signaling system is similar to this new system inasmuch as we automatically act in accordance to the red and green colors and life hangs in a balance and depends entirely upon universal acceptance and a total nonerroring participation. If we considered the realities and examined the statistics concerning the fatalities caused by people that fail to use the red traffic signal light our fears would make us become confined or isolated. In either situation we are not guaranteed anything but, in both situations there is a definite standardized pattern to observe, follow and dictate.

The blinking passing light will notify the vehicle to be passed of their intentions. It will also notify oncoming vehicles, which may not be seen easily during twilight conditions, what is transpiring. Since one second may be the difference between life and death, the blinking passing light may allow the oncoming vehicle to slow their speed in a courtesy manner or by drastic brake action which in either case may determine the difference between life and death.

When driving on multiple laned super type roads, the passing conditions are somewhat different from the conditions of two laned roads. Many accidents occur when an operator decides to pass either on the left or right without considering the faster moving vehicle behind them and in the lane they wish to use for their passing purposes. By and thru the adverse type of psychological timing a small damaging type of a glancing impact, or no impact at all, may cause a fast moving vehicle to loose control of their vehicle and careen across an island or medium into oncoming cars for the worst type of accidents.

Henceforth the hold light will be used in the same manner as for two laned roads with the exception that the hold light does not give anyone the right to change lanes without considering the faster moving vehicles behing them and in the lane they wish to use for their passing intentions.

If the time element does not permit the use of the hold light and if the operator illuminates the blinking passing light two seconds in advance to the first stage of the actual passing, these two seconds can also be life saving seconds.

Since most double filament bulbs have a high and low candle powered filament, the highest candled power filament may be used for the blinking green passing light. Consequently, the low candled filament may be used for the solid green hold light which may be left on to suit any existing passing condition. In a long line of vehicles and without the use of the hold light, the flashing lights would become very distracting.

In summary and in view of clarity and brevity, we have left out many novel construction type features so that a generalized understanding can be obtained by describing this custom made steering wheel which will receive two individual sets of multiple switches for the

express purpose of illuminating a green hold light or for illuminating a green flashing light while simultaneously a special and respective passing horn may be sounded to which a wide selection of volume may be used to suit any type of passing condition.

The National Safety Council provides information that substantiates the old saying that "Necessity is still the mother of invention" inasmuch as there were 13,000 intersection type fatalities in 1964, but in the 10 same year there were 14,000 passing fatalities.

Having established the nonclaimable and creative aspects of this invention which are the initial instigators for the structural means, other objects, aspects, features and advantages of the invention will become apparent during the ensuing description of preferred embodiments of the invention taken in conjunction with the accompanying drawings illustrative thereof, wherein:

FIG. 1 is a top plan view of an automobile provided with the audible and visual signaling and indicating system of this invention;

FIG. 2 is a schematic diagram of the electrical system constituting a part of the present invention;

FIG. 3 is an isometric view partially illustrating a steering column having a steering wheel rotatably mounted thereon, with such steering wheel being provided with the control electric switches of this invention and with portions of the electrical system being indicated in dashed outline (conventional horn rim absent in each and every drawing hereafter);

FIG. 4 is a top plan view of the steering wheel showing the same in dashed outline, and showing in full lines the electrical control switches and conduits for the associated electrical circuitry;

FIG. 5 is a fragmentary perspective view of a portion of the steering wheel and illustrating partially in dashed outline one of the two electrical control switches;

FIG. 6 is an enlarged fragmentary perspective view illustrating the structure shown in FIG. 5 with its associated structure being shown in exploded isometric form;

FIG. 7 is an isometric view of a switch case illustrating the slide switch button and the push button control that operates therethrough;

FIG. 8 is an exploded isometric view of one of the two dual single-pole, double-throw electric switches employed in the signaling system of this invention;

FIG. 9 is a central vertical sectional view of the 50 switch shown in FIG. 8 when the latter is in an assembled relationship;

FIG. 10 is a transverse sectional view of the switch case taken upon the plane of the section line 10-10 shown in FIG. 8;

FIG. 11 is a transverse sectional view of the switch taken upon the plane of the section line 11-11 shown in FIG. 9;

FIG. 12 is a side fragmentary view of the portion of the steering wheel that depicts a generalized relationship of the switch housing and its component parts whereby the dashed lines indicate the structural aspects;

FIG. 13 is a sectional view taken upon the plane of the section line 13-13 in FIG. 12;

FIGS. 14 and 15 are respectively side and bottom views of twin fillers shown in FIG. 6 which secures the switch assembly to and within the steering wheel;

FIG. 16 is an enlarged top view of a serration type detent system for retaining the grip knob (rim slide type) switch button in its adjusted position and, it is shown in an exploded detailed part view in FIG. 6;

FIG. 17 is an enlarged sectional detailed view of the lower portion of a steering wheel with its grip knob selector slide button and its connection to the switch components;

FIG. 18 is an enlarged top view of the mounting plate of insulative material as positioned and shown within the switch case in FIGS. 9 and 17;

FIG. 19 is an enlarged end view of the plate shown in FIG. 18 with a slide means for spacing and housing the actuatable contacts;

FIG. 20 is an enlarged top plan view of the means that is shown in FIG. 19 and FIG. 17 for grip knob slide button selection;

FIG. 21 is a bottom fragmentary view of a U-shaped detent plate with portions of its companion grip knob slide button being shown in dash lines, the view in effect being taken upon the plane of the juncture of such plate and the switch box housing;

FIG. 22 is a side elevational view of the portion of the steering wheel rim that contains the switch means to which dash lines indicate an approximate location of the switch for a generalized position;

FIG. 23 is a detail view of a steering wheel hub and the manner in which a swedged conduit type steering wheel spoke is welded to the hub of the steering wheel;

FIG. 24 is a sectional detail view of a structural tee connector at the juncture of the steering wheel spoke and the rim of the steering wheel;

FIG. 25 is a sectional detail taken upon the plane of the section line 25—25 shown in FIG. 24;

FIG. 26 is a sectional detail view of the structure for housing the switch assembly in the wheel rim and for connection the adjacent ends of solid and hollow steering wheel rim metallic sections;

FIG. 27 is a sectional view taken upon the plane of section line 27—27 in FIG. 4;

FIG. 28 is an elevational view of a steering wheel provided with a modified positioning of the electric control switches of the signaling system of this invention;

FIG. 29 is a sectional detail view illustrating with respect to the form of the invention shown in FIG. 28 the connection and welding of a swedged spike type conduit to the hub of the steering wheel;

FIGS. 30 and 31 are sectional detail views of the manner in which a tubular spike conduit is attached to a solid metallic reinforcement of the rim of the steering wheel shown in FIG. 28;

FIG. 32 illustrates in section a switch box housing which accommodates the electric switch assembly (such as is shown in FIG. 7) and in addition receives the threaded conduit type steering wheel spokes;

FIG. 33 illustrates a sectional view taken upon the plane of the section line 33—33 in FIG. 28;

FIGS. 34a, 34b and 34c through 37a, 37b and 37c illustrate part of the functions of the switch shown in FIG. 8 upon actuation of the slide button, push button and movable rim or spoke section;

FIGS. 38a, 38b and 38c through 40a, 40b and 40c illustrates part of the functions of a modified form of electric switch wherein the slide actuated by the movable portion of the wheel rim or spoke actuates the movement of an intermediate contact in addition to the pair of contacts;

FIG. 41 is a top plan view of a steering wheel illustrating in dashed outline the position of a rotary electric coupling by means of which electric circuits are connected between the switches on the rotatably mounted steering wheel, and as connected to the elements mounted in the stationary steering column of the automobile;

FIG. 42 illustrates in central section a rotary electric coupling with the two sections thereof displaced axially from each other for greater clarity;

FIG. 43 is an enlarged sectional detail view of a spring biased secondary contact carried by one of the conductor shells in the lower portion of the electric connector shown in FIG. 42;

FIG. 44 is a top plan view of the steering wheel shown in FIG. 42, and illustrating the coupling of the conductive shells thereof to electric conductors an in turn extending into the hollow wheel spoke type conduits;

FIG. 45 is a top plan view of the rotary electric connector shown in FIG. 42 with the steering wheel removed;

FIG. 46 through 50 illustrates the sequence stops performed in the making of a rotary electric connector such as shown in FIG. 42 by and through a metallic casting method;

FIG. 51 is a plan view on reduced scale of a portion of a mold.

FIG. 52 illustrates in central vertical section yet another embodiment of a rotary electric connector that is suitable for use in the signaling system of this invention, this view showing the upper and lower sections of such rotary electric connector axially separated for greater clarity;

FIG. 53 is an enlarged fragmentary top view of one of nine conductor rings as is seen from a top view of the stationary portion of the rotary electric connector in FIG. 52;

FIG. 54 is a side elevational view of the structure shown in FIG. 53;

FIG. 55 is an enlarged isometric view of the structure shown in FIGS. 53 and 54;

FIG. 56 is a top isometric detail view of the part 1,102 as shown in FIG. 52 in the upper rotatable portion;

FIG. 57 is a top plan view with duplications and similarity of FIG. 56;

FIG. 58 is a bottom plan view of the same part in FIGS. 56 and 57;

FIG. 59 is an isometric detail view of part 1104 as seen in FIG. 52 from a rearwardly position or from the underside thereof;

FIG. 60 is a bottom view with duplications and similarity to the view in FIG. 59. Dash lines indicate the ring groove that receives the outer diameter of the dust cover;

FIG. 61 is a top plan view of the same part shown in FIGS. 59 and 60 of which each of the nine rings shows its raised resilient locations;

FIG. 62 is an isometric detail view of a combination dust and wire bundle holder;

FIG. 63 is an enlarged front elevational view of a side element shown in FIG. 8;

FIG. 64 is a rear elevational view of the slide shown in FIG. 63, with a hidden detail being shown in dashed outline;

FIG. 65 is a side elevational view of the slide shown in FIGS. 63 and 64, with the opening therethrough being shown in dashed outline;

FIG. 66 is a bottom view of the structure shown in FIGS. 63, 64 and 65, with the hidden details being shown in dashed outline;

FIGS. 67, 68 and 69 are enlarged fragmentary detail views of an alternate form of means for positioning relatively movable elements, FIG. 67 illustrating a neutral relative position, and FIGS. 68 and 69 showing opposite limiting positions thereof; and,

FIGS. 70, 71 and 72; 73, 74 and 75; and 76, 77 and 78 are each sets of figures corresponding to the set of FIGS. 67, 68 and 69 with respect to other corresponding modifications.

Referring now to the drawings wherein like numerals designate like parts throughout the various views, the reference numeral 10 designates generally an automobile provided with a signaling system according to the present invention. The automobile 10 includes in addition to conventional electric sounding devices and visual lighting and signaling systems (none of which conventional structure is illustrated in the drawings) is provided with an electric sounding device 12 arranged to preferentially direct sound upon energization to the left side of the automobile 10 and preferentially also towards the front of the automobile 10. In a corresponding manner a second electric sounding device 14 is provided that preferentially directs upon energization sound to the right side and front of the automobile 10.

The automobile 10 is additionally provided with a pair of electric lamps 16 and 18 disposed respectively at the front left and rear left of the automobile 10 which are as presently described arranged to be continuously and concurrently continuously energized from a steering wheel mounted control, and a panel mounted indicator light 20 viewable from the position of the operator of the automobile 10 is arranged to be concurrently actuated with the electrical visual signal indicators or lamps 16 and 18. In a similar manner electric signal lamps or indicators 22 and 24 are respectively disposed at the right front and right rear of the automobile 10 and are by means presently to be described controlled for continuous and concurrent energization along with panel indicator 26 by a steering wheel control switch assembly.

A pair of visual signal lamps or indicators 28 and 30 are respectively disposed at the left front and left rear of the automobile 10 and are arranged to flash intermittently during a period of time under the control of the operator by a steering wheel mounted switch assembly. The lamps or visual indicators 28 and 30 are arranged with a panel lamp 32 so that the lamp 32, visible from the operator's position, flashes in synchronism with the visual signals 28 and 30.

A pair of visual signals or lamps 34 and 36 are respectively positioned at the right front and right rear of the automobile 10 and are associated with a panel visual indicator 38 to concurrently flash intermittently under the control of the automobile operator through the agency of a steering wheel mounted mechanism. Though the same could be provided, no necessity for providing panel indicators indicative of the operation of the horns or sounding devices 12 and 14 is likely to occur as the operator cannot only sense by hearing the

operation of such devices, their orientation and the relative loudness thereof.

While separate housings have been illustrated for each of the externally positioned visual indicators or lamps above described, such is not necessary as will be understood by those skilled in the art. Accordingly, while the pairs of signal lights 16 and 28, 18 and 30, 22 and 34, and 24 and 36 can be incorporated in single lamp housings respectively such as those of the egg crate type, it is important that the lamps as well as their corresponding panel indicators be uniquely colored as by using bulbs of colored glass or clear bulbs with appropriately colored light screens or filters whereby the signal indicators thus far described can be clearly distinguished from and not in any event confused with the conventional stop, parking, turning signal or running lights of conventionally and conventionally and universally understood usage. It is suggested for this purpose that the signaling devices 16, 18, 20, 22, 24 and 26 be a green color, and that the signaling devices 28, 30, 32, 34, 36 and 38 also be given a green color. Such selection of the colors will not in any manner conflict with or cause confusion with the white, amber and red colors presently employed with conventional signaling and driving indicators such as stop, parking, turn, fog and driving lights. It will be understood of course that the panel visual indicators 20, 26, 32 and 38 do not necessarily have to be colored as indicated (though this is preferred) as such panel indicators can be appropriately labeled, and their particular orientation on the instrument panel at the operator's position will afford a clear indication of such signal indicators as may be in operation. Preferably, none of the panel indicators should be of the color red as this might cause confusion with the red color customarily used in conventional constructions to indicate trouble or malfunction of various automobile components such as low oil pressure, inadequate generator or alternator operation. Such conventional trouble lights are ordinarily colored red and known somewhat in a derogatory fashion as "idiot" lights.

FIG. 2 illustrates schematically the electrical organization of the signaling devices, both audible and visual, thus far described. In FIG. 2, the reference numeral 40 designates a source of electrical energy such as a battery having one terminal grounded at 42. The other terminal of the battery 40 is connected by a lead 44 to branch leads 46 and 48 that are respectively connected to dual, single-pole, double-throw switches 50 and 52. As will be described in detail subsequently, the dual single-pole, double-throw switch 50 constitutes means whereby the lead 46 can be selectively connected electrically to terminals 54 and 56, and the lead 46 being normally disconnected from the terminals 54 and 56. Furthermore, the dual single-pole, double-throw switch comprises means whereby the lead 46 can be selectively connected electrically to terminals 58 and 60, the lead 46 normally being disconnected from the terminals 58 and 60. The dual single-pole, double-throw switch 50 serves the functions of selectively connecting the lead 46 to either of the leads 54 and 56 totally independent of the function of selectively connecting the lead 46 to the terminals 58 and 60 as will be clear upon subsequent description of the switch means 50.

The dual single-pole, double-throw switch means 52 is substantially identical to the switch means 50 and constitutes means whereby the lead 48 can be selec-

tively connected to terminals 62 and 64, though the lead 48 is normally disconnected from such terminals 62 and 64. Furthermore, the switch means 52 constitutes means whereby the lead 48 can be selectively connected to terminals 66 and 68, though the lead 48 is normally disconnected from the terminals 66 and 68. As in the case of the switch means 50, the operation of the switch 52 in connecting the lead 48 to the contacts or terminals 62 and 64 is totally independent of the operation of the switch means 52 to connect the lead 48 to the contacts or terminals 66 and 68.

The terminals 54, 56, 58, 60, 68, 66, 62 and 64 are respectively connected through a rotary electric connector designated generally at 70 and suggested schematically in FIG. 2 by a closed dashed block to leads 72, 74, 76, 78, 80, 82, 84 and 86. It will be noted that the power lead 44 is coupled between the battery 40 and the switches 50 and 52 through the rotary electric connector 70, and such portion of the power lead 44 extending between the battery 40 and the rotary electric connector 70 is indicated at 88. As an alternate and production economy method, power lead 44 may be divided or split from the power lead of the present used turn signal system.

The electric visual indicators or lamps 16, 18 and 20 are shown in FIG. 2 as being connected in parallel between the lead 76 and a grounded lead 90, whereby the lamps 16, 18 and 20 are concurrently energized. It will be evident to those skilled in the art that the electric indicators or lamps 16, 18 and 20 can be connected in series between the leads 76 and 90, whereby all or none of such lamps will function on the switch 50 connecting the lead 46 to the terminal 58, this serving to inform the automobile operator on failure of a visual signal by the lamp 20 that the lamps 16 and 18 are not operating. The parallel arrangement is preferred for the reason that it is deemed more important that the lamps 16 and 18 operate than that the automobile driver be informed of their failure to operate.

In a similar manner the lamps 22, 24 and 26 are connected in parallel between the lead 82 and the ground lead 90, whereby energization of such lamps is under the control of the switch means 52.

The lamps 28, 30 and 32 are connected in parallel between the lead 78 and the ground lead 90, whereby energization of such lamps can be controlled by the switch means 50. The operation of the lamps 28, 30 and 32 differs from the operation of the lamps 16, 18 and 20 in that a conventional flasher unit 92 is incorporated in the lead 78, whereby the lamps 28, 30 and 32 flash in unison under control of the flasher unit 92 when the switch means 50 is operated to connect the lead 46 to the terminal 60. As in the case of the lamps 16, 18 and 20, the lamps 28, 30 and 32 can be connected in series; however, the parallel arrangement is preferred for reasons indicated previously in relation to lamps 16, 18 and 20.

In an arrangement generally analogous to the relation of the lamps 16, 18, 20, 28, 30 and 32 to the switch means 50, the lamps 22, 24 and 26 are connected in parallel between the lead 82 and the ground lead 90, with the lamps 34, 36 and 38 being connected in parallel between the lead 80 and the ground lead 90, whereby the switch means 52 can be operated to connect the lead 48 to the terminal 66 to concurrently energize the lamps 22, 24 and 26, and to connect the lead 48 to the terminal 68 for concurrent energization of the

lamps 34, 36 and 38. A flasher unit 94 of conventional character is incorporated in the lead 80, whereby the lamps 34, 36 and 38 are flashed in unison during the time interval that the switch 52 is operated to connect the lead 48 to the terminal 68.

The directional electric sounding device or horn 12 is connected between the lead 72 and a grounded lead 96, whereby the horn 12 is energized on the switch means 50 being operated to connect the lead 46 to the terminal 54. The sounding device or horn 12 is also connected between the grounded lead 96 and the lead 74, it being noted that the latter is provided with a voltage dropping resistor 98 whereby the horn 12 can be energized on connection of the lead 46 to the terminal 56 through the lead 74, but at a lesser voltage than when the lead 46 is connected to the terminal 54. In other words, the sounding device or horn 12 can be energized upon connecting the lead 46 to either the terminal 54 or the terminal 56, but the sounding device or horn 12 will produce a lesser volume of sound when the lead 46 is connected to the terminal 56 than when the lead 46 is connected to the terminal 54. It will be obvious to those skilled in the art that many other alternatives than the illustrated and described arrangement can be provided whereby relatively loud and soft sounds are electrically produced upon the lead 46 being selectively connected to the terminals 54 and 56, respectively. An obvious alternative would be to provide two separate horns of differing loudness, but this would not be as economical as a system employing only a single sounding device. Since electric sounding devices or horns of conventional character may draw such heavy currents as possibly to be damaging to switches and sliding contacts, as is well known in the art, it is deemed well within the province of the capabilities of those familiar with the art to provide the lead 72 with a current controlling relay as well as the lead 74 with a current controlling relay for such purposes, it being understood that the relay controlled by the lead 74 would appropriately be provided with a current or voltage reducing resistor or the like.

As in the case of the electric sounding device or horn 12, the horn 14 is connected between the lead 84 and the ground lead 96, as well as between the lead 86 and the ground lead 96, it being noted that the lead 86 is provided with a voltage dropping resistor 100 for the same purpose as the previously described resistor 98. Accordingly, operation of the switch means 52 to connect the lead 48 selectively with the terminals 62 and 64 will cause relatively loud and relatively soft sounding by the directional sounding device or horn 14.

THE DUAL, SINGLE-POLE, DOUBLE-THROW SWITCH

The automobile 10 includes a conventional steering wheel designated generally at 102 mounted for rotation upon a steering post 104, the steering wheel 102 including a hub portion 106 that is connected by radially extending spokes 108 and 110 to a peripheral steering wheel rim 112.

As clearly shown in FIG. 3, the dual, single-pole, double-throw switch means 50 and 52 are respectively mounted in left and right hand portions of the steering wheel rim 112, respectively. By left and right hand portions of the peripheral rim 112 of the steering wheel 102, it is meant that portions of the rim 112 are respectively disposed at the left hand and at the right hand of

the operator when the steering wheel 102 is in its neutral position, that is, the position rotatably occupied by the steering wheel 102 when the automobile 10 is being driven straight ahead. In other words, when the automobile is being driven straight or nearly straight ahead, the switch means 50 is to the driver's left and the switch means 52 is to the driver's right.

Inasmuch as the switch means 50 and 52 are substantially identical and differ primarily only in their locations upon the steering wheel 102, a detailed description of the switch means 52 will suffice for both.

As best shown in FIG. 8, the dual, single-pole, double-throw switch means 52 comprises a case 102 which has a central hollow metallic section comprised of side walls 122 and 124, and top and bottom walls 126 and 128, respectively. The case 120 also includes an arcuate or cylindrical rear wall or cap 130 having integral top and bottom wall portions 132 and 134, respectively. When the housing 126 is assembled, the rear section thereof constituted of the rear wall 130 and the tip and bottom wall portions 132 and 134 tightly receive the rear marginal portions of the side walls 122 and 124, and the top and bottom walls 126 and 128, with the housing 120 being releasably retained in assembled relation (such as shown in FIG. 9) by mating and locking engagement of detents carried by the rear section of the case 120 such as those indicated at 136 and 138 with recesses in the side and bottom walls 122, 124 and 128 such as those indicated at 140 and 142.

The open front end of the metallic elements of the case 120 thus far described is closed by a metallic plate 144 of rectangular configuration that is welded to the walls 122 and 124 of the case 120 as indicated at 146 in FIGS. 9 and 11; it being noted that the plate 144 projects peripherally about the housing 126 to afford a means for mounting the case 120 that will subsequently be described.

A mounting plate 150 of electrically insulative material such as Bakelite or Lucite is mounted within the housing 120 in spaced relation above the bottom wall 128, the mounting plate 150 being retained in assembled position shown in FIG. 9 by means of screws 152 and mounting posts 154, the mounting posts 154 having enlarged upper ends that are embedded in the plate 150 as shown at 156 so that the posts 154 depend from the plate 150. The lower ends of the posts 154 are provided with internally threaded openings 158 which threadingly receive the screws 152. The screws 152 extend through dimpled apertures 160 in the bottom wall 128 in an arrangement such that the screws 152 are flush with the lower surface of the bottom wall 128, as shown.

Spaced along a line perpendicular to the front rectangular plate 144 centrally of the case 120 and the mounting plate 150 are a pair of contacts 160 and 162, such contacts 160 and 162 being fixed on the upper side of the plate 150 and retained by means of terminals 164 and 166 extending downwardly through suitable apertures 168 and 170, respectively, in the mounting plate 150. The terminals 164 and 166 are connected electrically by an electrical lead 172A that is recessed in a suitable slot 172 in the underside of the mounting plate 150. Thus, the lower end portion of the terminal 164 projects into slot 172 of the plate 150 which constitutes a terminal to which the power lead 44 (see FIG. 2) is connected. It will be evident from the

preceding that the contacts 160 and 162 constitute the pole of switch means 52 designated at 174 in FIG. 2.

As best shown in FIGS. 8, 9 and 18, dashed line 172 represents a recessed slot which houses the conductor wire 172A (best shown in FIG. 9). As best seen in FIG. 8, contact plate 150 is provided with an aperture 170 which receives an insulated bushing 171; this insulated bushing receives the contact post 166 of the contact 162. Said post 166 projects into the slot 172 but not beyond the flat bottom surface of contact plate 150 so that the flat surface of the slide 300 locates against the flat and now the unobstructionable surface of the contact plate 150. Said insulated bushing 171 permits intense heat to be applied to the head of the contact 162 so that conduction facilitates a good solder joint at its remote end of the conductor 172A in the recessed slot 172.

In addition to the lead 172, the contacts 160 and 162 are connected by an integral conductive strip 173. If desired, as will be evident, either the lead 172 or the strip 173 may be omitted.

A pair of contacts 176 and 178 are spaced upon opposite sides of the contact 160 along a line parallel to the front plate 144, such contacts 176 and 178 being fixedly secured to the plate 150 by means of the terminals 66 and 68 extending downwardly through the plate 150, such terminals 66 and 68 having been previously described in connection with FIG. 2.

Means is provided to selectively electrically bridge the contact 160 to either the contact 176 or the contact 178. Such means comprises a slide 180 of electrically insulative material mounted above the plate 150 for horizontal sliding linear movement along a horizontal line parallel to the front wall or plate 144. The slide 180 has fixed thereto a depending wiper contact 182 that is in sliding engagement with the upper surface of the contact 160 and which upon appropriate sliding movement of the slide 180 selectively bridges the contact 160 to the contacts 176 or 178, it being understood that the wiper contact 182 is in engagement solely with the contact 160 when the slide 180 is in the neutral or central portion of its range of movement.

Preferably, the wiper contact 182 is an annular metallic disc slidably disposed upon a depending post 184 carried by the slide 180, with a spring washer 186 disposed on the post 184 intermediate the slide 180 and the wiper contact 182 to resiliently urge the latter downwardly towards its sliding engagement with the contacts 160, 176 and 178. In a method of construction, the post 184 has an enlarged upper end portion that is fixedly embedded or threaded into the body of the slide 180 as clearly shown in FIG. 9. In preferred construction and in view of production, slide 180 may be made from a single piece of nylon, to which the post 184 will be integral.

By means presently to be described, a rectangular plate 188 of electrically insulative material overlies and is secured to the previously described metallic front wall or plate 144. Elongated and horizontally extending registering slots 190 and 192 are provided in the plates 188 and 144, respectively. The slide 180 is provided with a horizontally elongated boss 194 that projects horizontally toward the front of the housing 120 and through the slots 190 and 192, the slide 180 being provided with shoulders 196 and 198 above and below the base of the boss 194 that slidably engaged the internal surface of the front wall plate 144 during the previously

described movement of the slide 180, it being understood that the horizontal extremities of the slots 190 and 192 limit the horizontal movement of the slide 180 by coaction with the boss 194.

A slide button 200 is slidably seated against the plate 188, such slide button 200 being provided, as best shown in FIG. 9, with an elongated slot 202 therein to accommodate with a snug fit the boss 194 therein. The slide button 200 is secured to the slide 180 by means of a set screw 204 (see FIG. 7) that is threaded into aligned and internally threaded apertures 206 and 208 in the slide button 200 and the boss 194.

As thus far described, it will be evident that the slide button 200 can be manipulated to move the slide 180 so as to cause the wiper contact 182 to move from a position contacting solely the contact 160 so as to selectively bridge the latter with either the contact 176 or 178.

A ball 210 and a compression spring 212 are biased between the adjacent sides of the plate 188 and the slide button 200 and received in a teardrop concaved recess 213 therein in an arrangement tending to urge sliding movement of the push button 200 and consequently the slide 180 to their neutral positions such that the wiper contact 182 engages solely the contact 160. The apertures 214 in the underside of slide button 200 is best shown and positioned in FIG. 11 by dashed lines. Preferably additional means are provided for releasably retaining the slide 180 at either of the limits of its guided movement so that when, for example, the slide button 200 is manipulated to cause the wiper contact 182 to bridge the contact 160 to the contact 176, the slide button 200 and the slide 180 controlled thereby remain in such position until sufficient finger pressure is brought against the side button 200 to urge the same towards its neutral position. Such additional and optional provision comprises a pair of balls 220 and 222 respectively associated with compression springs 224 and 226, such balls and springs being under compression between the plate 188 and the slide button 200 and received in recesses 228 and 230 in the slide button 200 so as to move along with the latter. The plate 188 (see FIG. 8) is provided with a pair of concave recesses 232 and 234 having a greater spacing than the recesses 228 and 230 (best shown in FIG. 11) and arranged so that the ball 220 is received in the recess 234 solely when the slide button 200 is at the leftward limit of its movement and so that the ball 222 is received in the recess 232 solely when the slide 200 is at its furthest position to the right, as seen in FIG. 8. Such described and illustrated additional and optional provision results in the slide button 200 remaining in either of its limiting positions, but tending otherwise to be urged and yieldingly retained in its neutral or center position.

As best shown in FIG. 11, the apertured portions 214, 228 and 230 of the slide button 200 which houses the said detent balls and springs are shown in their counterbalancing relationship to which the larger ball and spring further counteracts the two smaller balls and springs. As previously stated and in a similarity to the concave teardrop recess 213, recesses 232 and 234 also tend to urge the slide button 200 for a quick and easy manipulation.

The parts of the switch means 52 thus far described enables the performance of the switch functions previously described in connection with FIG. 2 in that the lead 44 can be selectively connected to either of the

terminals 66 or 68 so as to selectively energize the lamps 22, 24 and 26 continuously during the interval that the lead 44 is connected to the contact or terminal 66 or to intermittently energize or flash the lamps 34, 36 and 38 during an interval that the lead 44 is connected to the contact or terminal 68.

Proceeding now to a description of the means whereby switch means 52 can be actuated to selectively connect the lead 44 to the contacts or terminals 62 or 64, a slide 240 of electrically insulative material is mounted within the housing 120 for linear sliding movement along a line perpendicular to the front wall or plate 144 of the housing 120.

The slide 240 is generally U-shaped and includes a web portion 242 and spaced legs 244 and 246 that extend toward the front plate 144. The slide 240 is spaced above the mounting plate 150 and is slidably supported and guided for movement by means of inwardly struck or stamped pairs of spaced ribs 248 and 250 in the side walls 122 and 124, respectively, of the housing 120. The legs 244 and 246 of the slide 240 are respectively received between the pairs of ribs 248 and 250. The slide 240 is resiliently urged from the rear wall 130 toward the front wall or plate 144 by means of a coiled compression spring 252 having one end seated within a recess 254 formed in the web 242 of the slide 240. The coiled compression spring 252 is retained against lateral displacement by means of a countersink rivet 256 that is welded to the cap 130 of the later to be assembled case 120, after being placed through an internal dimpled aperture 258 in the rear wall 130, such rivet 256 having a cylindrical extension projecting through the coiled spring 252 into the recess 254. Said rivet may have threads as shown or may be made to suit. The web portion 242 of the slide 240 is provided with a depending wiper contact structure generally similar to that previously described in connection with the slide 180. The wiper contact for the slide 240 is of annular configuration and is designated by the reference numeral 260, the wiper contact 260 being slidable upon a depending mounting post 262 fixed to the slide 240, with a resilient washer 264 being disposed about the mounting post 262 intermediate the slide 240 and the wiper contact 260 to resiliently urge the latter downwardly into sliding engagement with the previously described contact 162 carried by the mounting plate 150. In an alternate and preferred method of construction, slide 240 may be made from a single piece of nylon, to which mounting post 262 will be integral.

Push button 274 is provided for enabling the user to manipulate the slide 240 against the yielding force of the spring 252 whereby the slide 240 can be moved horizontally from the front wall or plate 144 for a purpose to subsequently become apparent. Such structure comprises the slide 180 being bifurcated as indicated at 266, whereby the web 280 of the slide 240 is received within such bifurcation with non-interfering clearance function.

As best shown in FIGS. 8 and 9, a push button stem 270 slidably extends through a circular opening 272 in the slide 180 and the boss 194 thereof. The pin 270 is provided at its forward end with a head portion 274 that in transverse section is of elongated configuration, and such head portion 274 is received within an elongated slot 275 for longitudinal movement. The end of the push button stem 270 remote from the push button or head 274 projects between the bifurcations of the

slide 180 and is threadingly engaged in an internally threaded nut or sleeve 276 to limit outward movement of the push button 274 and its stem 270, it being noted that the rear end of the nut or collar 276 is provided with a small kerf 278 whereby the nut 276 can be adjusted upon the threaded end of the push button stem 270.

The previously described structure is so arranged that the end of the nut or collar 276 remote from the push button 274 slidably engages the edge 280 of the web 242 facing toward the front wall or plate 144. When the slide 240 is urged to its most forward position by the spring 252, the length of the push button stem 270 is such that engagement of the slide 240 with the nut 276 causes the push button 274 to project forwardly for a short distance ahead of the slide button 200 as shown in FIG. 7. As will be evident, the push button 274 can be depressed from a position shown thereof in FIG. 7 to cause the slide 240 to move rearwardly against the resilient force of the spring 252 for a purpose to become clear presently.

By engagement with the bottom of the slot defined as the bifurcated form of the slide 180 (the slot 266 being wider than the diameter of the circular opening 272) the nut 276 serves a multiple purpose or function of which will be described as follows:

Said nut when adjusted to and on the stem 270, retains, positions and limits the uppermost thrust caused from the coiled spring 252 so that the head of push button 274 does not leave the counterbored slot 275.

When push button 274 is depressed, said nut becomes a thrust type nut (of which at all times nests on the web 280 of the slide 240) and depresses slide 240 in a rearwardly and linear movement opposite and perpendicular to the plate 188. Upon said activation of the push button 274, the bottom of the counterbored slot 276 serves as a limit stop when the rearward side of the push button 274 is contacted to accomplish the desired switch function.

Said nut is obviously larger in diameter than the circular aperture 272 that extends through a thin web 273 in the bottom of the counterbored slot 275 (See FIG. 66). From the foregoing description, the stem 270 of the push button 274 is guided by the circular aperture 272 along with guided movements between the head of the push button 274 to the counterbored slot 275.

Yet another slide 300 of electrically nonconductive or insulative material is mounted for linear sliding movement within the housing 120, such slide 300 being disposed below the end of the mounting plate 150 remote from the front wall or plate 144. The slide 300 is mounted for linear sliding movement horizontally in a direction parallel to the front wall or plate 144, that is, in a direction perpendicular to the direction of movement of the slide 240 and parallel to the movement of the slide 180. The means for guiding and supporting the slide 300 for limited linear movement of the character described comprises an elongated slot 302 through the mounting plate 150 parallel to the front wall 144. A pair of vertical posts constituting the previously described contacts or terminals 62 and 64 extend slidably through the slot 302 (see FIG. 2), and the upper ends of the terminal posts 62 and 64 are provided with contacts 304 and 306, respectively, that are spaced from each other and which are enlarged and in sliding contact with the upper surface of the mounting plate 150 about the slot 302. The lower ends of the posts or terminals

62 and 64 extend through vertical openings 308 and 310 through the slide 300, and nuts 312 and 314 are threaded upon the lower ends of the terminal posts 62 and 64 projecting below the slide 300 to adjust and retain the slide 300 against the underside of the mounting plate 150. The slot 302 is greater in length than the spacing of the terminal posts 62 and 64, and the terminal posts 62 and 64 have a diameter so as to make a sliding fit in the slot 302, whereby linear motion of the slide 300 of the character above specified is guided by the terminal posts 62 and 64 in the slot 302, it being noted that the contacts 304 and 306 move in unison with the slide 300.

It will be noted that the contacts 304 and 306 are disposed along a horizontal line that is parallel to the front wall or plate 144, and that the contacts 304 and 306 are spaced along such line with the contacts 304 and 306 also being adjacent to but spaced slightly rearwardly of the contact 162 fixed to the mounting plate 150.

The arrangement is such that the wiper contact 260 (which is in continuous engagement with the contact 162 throughout the range of movement of the slide 240) can engage either of the contacts 304 or 306 when and only when the slide 240 is moved to its rearmost position as manually actuated by depression of the push button 274. Furthermore, the spacing of the contacts 304 and 306 is such that when the slide 240 is in its rearmost position as caused by depression of the push button 274, the wiper contact 260 contacts only the contact 304 when the slide 300 is adjacent one end of its guided travel path, and engages only the contact 306 when the slide 300 is adjacent the other limit of its travel path, with neither of the contacts 304 and 306 being in engagement with the wiper contact 260 when the slide 300 is midway between its extremes of movement.

From the foregoing it will be apparent that the wiper contact 260 can be caused to electrically bridge the contact 162 selectively to the contacts 304 or 306 upon the concurrence of the push button 274 being depressed and the slide 300 being displaced an interval one way or the other from its central or midway position.

Means is provided on the side of the case 120 remote from the slide and push buttons 200 and 274 for manually actuating movement of the slide 300.

Such means for manually actuating movement of the slide 300 comprises an elongated threaded member 340 having one end threaded tightly in the slide 300 as indicated at 342 in FIGS. 8 and 9, with the elongated member 340 extending horizontally and rearwardly from the slide 300 through an elongated slot 344 (see FIG. 8) to project rearwardly from the rear wall 130 of the case 120. The arrangement is such that the slot 344 will permit the portion of the elongated member 340 disposed externally of the housing 120 enables actuation of sliding movement of the slide 300 from a position external of the case 120. Means will presently be described whereby the extremity of the elongated member 340 external of the case 120 is coupled to a relatively movable segment or portion of the steering wheel whereby manipulation of the member 340 and the slide 300 can be effected manually.

An opening is provided in the bottom wall of the case 120 whereby insulated electrical conductors may extend into the lower portion of the case 120, such opening being defined (when the case 120 is assembled) by

arcuate cutout areas in the overlapping regions of the bottom wall 128 and the bottom wall 134 of the rear section of the case 120. The arcuate cutaway portion of the bottom wall 134 of the rear section of the case 120 is indicated at 350 in FIG. 8. The arcuate cutaway portion of the bottom wall 128 of the front section of the case 120 is indicated at 352 in FIG. 8. Accordingly, the opening in the bottom of the housing 120 defined by the cutout portions 350 and 352 of the bottom walls 134 and 128, respectively, enable leads 48, 84, 86, 80 and 82 to be brought in from a position external of the case 120 into the case 120 for respective connection to the terminals (174 as seen in FIG. 2 — effectively 164 in FIG. 9), 62, 64, 68 and 66. The means for mounting the switch means 52 and its external electrical connections will now be described.

MEANS CARRIED BY THE STEERING WHEEL FOR MOUNTING THE SWITCH MEANS AND PROVIDING EXTERNAL CONNECTIONS FOR THE SWITCH

The steering wheel 102 is, except as specifically pointed out hereinafter, conventional in construction. Those familiar with conventional steering wheels will readily appreciate that the same are usually of integral composite character, that is, the spokes and the peripheral rim include a metallic frame of welded or otherwise integral construction about which is molded a synthetic resin or hard rubber material having the desired external configuration. This is generally true whether the steering wheel is flat or of the recessed hub type currently popular in today's passenger automobiles for safety reasons. The internal metal (usually steel) framework of the spokes and the peripheral rim is usually solid rather than tubular in construction, and it will become evident presently that the hereinafter described preferred construction according to the invention is compatible with either of such conventional structural arrangements.

As best shown in FIGS. 4 and 6, the steering wheel 102 has the spokes 108 and 110 thereof provided with central metallic and tubular elements (preferably aluminum) 360 and 362 which replace the conventional steel cores of steering wheel spokes. The adjacent ends of the tubular elements 360 and 362 are rigidly secured to the steering wheel hub 106 as by welding or the like. The remote ends of the tubular elements 360 and 362 are provided with special "T" fittings 364 and 366, respectively (see FIG. 24). The "T" fittings 364 and 366 are threaded upon the tubular members 360 and 362, whereby the interior of each of the tubular members affords communication with the interior of its associated "T" fitting. As best shown in FIG. 24 in connection with the "T" fitting 366 (it being understood that the "T" fittings 364 and 366 are similar) the "T" fitting 366 is partially solid in the interior thereof to define an internal inclined surface 370 facing toward internally threaded ports or openings 372 and 374 that are at right angles to each other. It will be noted that the internally threaded opening 372 is at the base of the "T" configuration of the fitting 366 and is such as to threadingly receive and engage the tubular member 362. The end of the "T" fitting 366 designated at 376 which is remote from the internally threaded opening 374 and at right angles to the internally threaded opening 372 is provided with a conically tapered recess 377 therein.

An arcuate, substantially semi-circular length of solid aluminum rod 380 is provided to constitute the metallic

core of the lower portion of the rim of the steering wheel 112 as shown in FIG. 4, and the opposite ends of the rod 380 are tapered as indicated at 382 in FIG. 24 to be received within the recesses of the "T" fittings 364 and 366, such rod 380 being welded to such "T" fittings as indicated at 384 in FIG. 24.

A special switchbox casing or housing designated generally at 400 is provided for partially housing the previously described switch means 52. As best shown in FIGS. 6 and 26, such metallic casing (preferably aluminum) 400 is elongated and of substantially a D-shape in transverse section so as to have a flat face 402 on one side thereof as shown in FIG. 6. The casing 400 is hollow so as to define an internal chamber 404 that opens through the flat face 402 of the casing 400. One end of the casing 400 is provided with an internally threaded opening 406 by means of which the casing 400 is threaded upon a short length of metallic tubular member 410, with the other end of the tubular member 410 being threadingly received within the previously described internally threaded opening 374 in the "T" fitting 366. The arrangement is such that the chamber 404 has communication with the interior of the tubular member 362 through the tubular member 410 and the interior of the "T" fitting 366. The other end of the hollow casing 400 that is remote from the internally threaded opening 406 is closed and provided with a conically tapered recess 414 therein. An elongated arcuate rod 416 has one end received within the recess 414 and is welded to the case 400 as indicated at 418. The other end of the rod 416 is similarly secured to a casing 420 and the latter is connected in turn to the "T" fitting 364 by a metallic tubular member 422, it being understood that the casing 420 is similar to the previously described casing 400 and that the tubular member 422 is generally like the previously described tubular member 410 and bears the same relation to the "T" fitting 364 and casing 420 that the tubular member 410 bears to the "T" fitting 366 and casing 400.

The switch box housing or casing receives the assembled switch means after a cable is inserted through the conduit system, which in turn pulls the wire bundle 361 down through the system until the assembled switch means is received into the boxed cavity called a switch box casing or housing. These electric conductors are then soldered to tab screws 942 and 926, as shown in FIG. 42. Slack wires can then be coiled here and covered by the horn rim.

As best shown in FIG. 6, the assembled switch means is received within the hollow housing 400 so that the front wall plate 144 seats against the flat face 402 of the housing 400, and the switch assembly 52 is secured to the housing 400 by means of self-tapping screws 460 slidably extended through recessed openings 462 in a pair of arcuate securing plates or filler members 464 and 466 disposed on opposite sides of the slide button 200, as well as through openings 468 in the plates 188 and 144 into openings 470 in the casing 400. The screws 460 are self-tapped and threaded in the openings 470. The mounting plates 464 and 466 slidably receive the slide button 200 therebetween and are of such a height as to protect the slide button 200 against any inadvertent forces striking the same laterally with respect to the sliding movement of the slide button 200. Preferably, the mounting plates 464 and 466 are made of a synthetic resin.

In general it is preferred that the assembly of the switch means 52 with the casing 400 (as well as assembly of the switch means 50 with respect to the casing 420) be deferred until such time as the metallic frame of the steering wheel 102 has the conventional sheath of hard rubber or synthetic resin molded thereabout; it being appreciated that such metallic frame of the steering wheel 102 is constituted to the hub 106, the radially extending, spoke defining tubular members 360 and 362, the "T" fittings 364 and 366, the arcuate rod 380, the tubular members 422 and 410, the casings 420, and the arcuate rod 416. It is preferred that during the conventional molding of the hard rubber or synthetic resin sheath 500 about the wheel frame just defined that a masking plate (not shown) be placed over the hollow chambers of the casings 400 and 420 to prevent the ingress of the material 500 molded about the metallic frame of the steering wheel 102, it being obvious that the radial inwardly ends of the tubular members 360 and 362 are similarly protected against the ingress of the material being molded about the metallic frame to constitute the sheath 500.

After the sheath 500 of hard rubber or synthetic resin has been molded as an integral unit about the metallic frame of the steering wheel 102, the previously mentioned shield plates are removed from the casings 400 and 420 so that the flat surface 402 of the casing 400 and a corresponding surface of the casing 420 is exposed, whereby the switch means 52 can be assembled in the casing 400 in the manner previously described, it being understood that the opposite lateral faces 504 and 506 of the plates 464 and 466 seat against opposing faces 508 and 510, respectively, of the sheath 500. It will be noted that the upper surfaces of the plates 464 and 466 are so contoured as to smoothly merge with adjacent exterior surfaces of the sheath 500 of the steering wheel 102, as seen in FIG. 6.

As best shown in FIG. 26, the side of the housing 400 opposite the flat face 402 is provided with an elongated slot 520 therethrough, such elongated slot 520 accommodating the threaded member 340 (see FIG. 6) therethrough. A portion of the sheath 500 is cut away on the under side thereof opposite the flat face 402 of the casing 400 to define (see FIG. 6 and 17) a recess having a flat bottom wall or surface 600 and opposed flat side walls or surfaces 602 and 604, the surfaces 602 and 604 being perpendicular to the surface of the face 600. It will be noted that the flat face 402 (which is preferably essentially parallel to the plane of the rim of the steering wheel and which faces toward the operator) is parallel to the flat surface 600. The side of the housing 400 opposite the face 402 is substantially tangent to the surface 600 (or the same is milled, cast or otherwise given an external configuration such as to lie in the plane of the surface 600). It will also be noted that, as is conventional, the sheath 500 of the steering wheel 102 has an undulating or serpentine surface 610 on the side thereof corresponding to the side of the cutout defined by the surfaces 600, 602 and 604. As shown, it is preferred that the surfaces 602 and 604 coincide with ridges of such serpentine surface 610, as best shown in FIG. 17.

A U-shaped steel detent plate, generally designated at 615, including a flat web 616 and legs 618 and 620 is fitted within the cutout portion of the sheath 500 with the web 616 being seated against the surface 600 (and the housing 400), with the legs 618 and 620 being

respectively seated against the surfaces 602 and 604, as shown in FIGS. 6 and 17.

A grip knob slide selector or slide member 624 (preferably metallic) with external serrations having a configuration generally conforming to the cutout portion of the sheath 500 defined by the surfaces 650, 602A and 604A, as best shown in FIG. 6, is provided and slidably received within the U-shaped member defined by the web 616, and the legs 618 and 620. Henceforth, the detent plate 615, which has a flat web surface 616, will nest against the surface 600 of the switch box casting 400 in a manner in which the capped apertures 656A and 658A will receive the projections or tits 656 and 658 of the switch box casting 400.

As also shown in FIGS. 6 and 17, the bosses 656A and 658A may be formed as from a blanking operation, since the thickness of said plate is in extreme exaggeration. In the event that said apertures are not stamped or blanked, and in a preferred construction, said apertures may be drilled so that no capped dimpled projections will be evident. Henceforth, tits 656 and 658 will limit the horizontal slide action of the slide 624. In the blanked method of making 656A and 658A capped recesses, the outside diameter of capped recesses limits said movement from the extremities of the elongated slots 652 and 654. It will be noted that the slide member 624 has an external surface that smoothly merges with contiguous external surface portions of the sheath 500 and in particular includes an undulating surface 630 constituting a continuation of the undulating surface 610, the undulating surface 630 of the slide member 624 having a length such that a ridge occurs at the midpoint of its length along the periphery of the steering wheel rim, such ridge being designated at 632 in FIG. 17.

The flat web portion 616 is provided with an elongated opening 634 through which the elongated threaded member 340 slidably extends so as to accommodate sliding movement of the member 340 laterally and in a direction normal to the view shown in FIG. 17. It will be noted upon inspection of FIGS. 17, 26 and 6 that the surface 600 is preferably tangent to the casing 400 and that any intervening material of the sheath 500 in alignment with the slots 520 (FIG. 26) and 634 is removed so as to permit the lateral movement of the member 340 previously described.

The slide member 624 is provided with a recessed opening 640 into which the headed end 642 of the member 340 is firmly seated, the arrangement being such that sliding movement of the slide member 624 in a direction perpendicular to the plane of the view of FIG. 17 will impart the previously described movement or motion to the member 340 and thence to the slide 300.

In order to limit sliding movement of the slide member 624 within the U-shaped detent plate defined by the web 616 and the legs 618 and 620, the surface of the slide member facing toward the web 616 indicated at 650 is provided with a pair of spaced parallel recesses 652 and 654 that are elongated and which receive in a sliding and guiding fashion tits 656 and 658 which are formed integrally on the switch box housing 400, as best seen in FIG. 17. The tits or projection lugs 656 and 658 are of the same material as the housing 400 and can be cast herewith or machined thereafter. In assembling, the detent plate 615 in which apertures 656A and 658A are received by the lugs 656 and 658,

in a press fit manner, until the flat surface of the dent plate 616 is mated against the flat surface 600. The arrangement of the recesses or grooves 652 and 654 in relation to the tits 656 and 658 of the switch box housing 400 is such that one limit of sliding movement permitted to slide 624 corresponds with the slide 300 being positioned so that the contact 304 is engageable with the wiper contact 260 and at the other extreme of movement the contact 306 its engageable by the wiper contact 260. At a position midway between such extremes of movement neither of the contacts 304 and 306 are engageable by the wiper contact 260 by virtue of the spacing of the contacts 304 and 306.

As best seen in FIG. 17, the U-shaped dentnt plate has outward projections on legs 618 and 620 which are respectively the dimpled recess and the struck portions of the dimpled teeth. In the preferred construction, said projections are received into clearance reliefs 700 of the sheath 500 by a small marginal clearance as shown or with a larger clearance to suit fabrication.

Means is provided whereby the slide 624 tends when at its midway position to remain in such midway position; however, the slide 624 will be urged toward and tend to remain in either of its limiting positions when initially removed towards such limiting position by a short interval from its midway position. Such means will be best appreciated upon reference to FIGS. 6, 12, 16, 17 and 21, wherein it will be seen that the leg 618 is provided with a dimpled recess 722 (FIG. 17) that is stamped thereinto, and the opposite inner face of such recess is provided with a series of dimpled or blunt upstanding teeth 702 that cooperate with a toothed cam element 706 (FIG. 16) that is slidingly received within a recess 710 in an end of the slide member 624 facing toward the leg 620, the cam element 706 being spring biased toward the leg 620 by means of a compression spring 712 disposed in the recess 710 and seated between the bottom of the latter and the cam element 706. The cam element 706 is provided with a series of teeth 714, 716 and 718 that coact with the struck teeth 702 from the recess 710. The arrangement is such that when the slide 624 is in its central or midway position the tips of the teeth 714, 716 and 718 directly oppose the blunt ends of the teeth 702 so that the coaction between the cam element 706 and the teeth 702 is in a stable state with no force being exerted that would tend to shift the slide 624 from its central or neutral position. The slide 624 tends to be retained in its intermediate or neutral position by virtue of a spring pressed ball 720 carried at the other end of the slide 624 remote from the cam element 706 being engaged in a spherical recess 722 in the leg 618. The ball 720 is received in a recess 724 in the slide 624 and is urged outwardly therefrom by a coiled compression spring 726. Accordingly, the ball 720 coacts with the recess 722 to yieldingly retain the slide 624 in its central or neutral position; however, when the slide 624 is urged toward one of its limiting positions sufficiently to at least partially disengage the ball 720 from the dimpled recess 722 and also to move the teeth of the cam element 706 from direct opposition against the blunt or flat tips of the teeth 702, the teeth of the cam element 706 coact with the teeth 702 to cam the slide 624 fully to its limiting position. In a similar manner movement of the slide 624 a slight distance in the other direction from its neutral position results in the teeth of the cam element 706 coacting with the teeth 702 to cam the slide member 624

to its other limiting position. From either of its limiting positions, the slide member 624 can be moved to its neutral position and will be retained at such position by the previously mentioned coaction of the ball 720 and the recess 722, it being again noted that no camming effect is produced by the teeth of the cam element 706 and the teeth 702 will occur when the slide 624 is in its limiting position as the teeth of the cam element 706 bear directly against the flat or blunt ends of the teeth 702.

Alternatively, the teeth 702 and the teeth of the cam element 706 can be so arranged as to be fully meshed when the slide 624 is in its nautral position, with the tapered sides of the teeth of the two sets coacting upon the spring biased movement of the teeth of the cam element 706 against the teeth 702 urging precise meshing of the teeth and correct positioning of the slide 624 at its central or neutral location. Lateral displacement of the slide 624 is resisted by the camming effect between the two sets of teeth until the teeth are in direct opposition with further lateral movement being thereafter assisted by the teeth camming against each other and moving again into a meshing relation to reach a final position in which the slide 624 has been laterally displaced an interval precisely equal to the spacing between the teeth 702 (this also being equal to the spacing of the teeth on the cam element 706 as such teeth are equally spaced). It will be appreciated that the slide 624 is in a stable position at any time that the teeth are in mesh and the slide 624 is secure against slipping laterally, lateral movement of the slide 624 from any of its stable positions requiring a positive application of pressure against the slide 624. In a similar manner the slide 624 can be laterally displaced in the opposite direction from its central or enutral position in such a manner that the teeth are cammed apart until the teeth are in direct opposition after which further lateral displacement of the slide 624 is assisted by camming action between the teeth as the teeth again approach and reach fully meshed relationship corresponding to displacement from the neutral position by a precise interval determined by the spacing of the individual teeth in each set thereof. It will be noted that this alternative arrangement of the teeth 702 and the teeth of the cam element 706 is capable of advantageous employment when it is desired that the slide 624 (or even more importantly the wiper contact actuated thereby) occupy more than three stable positions each equidistantly spaced. Such an arrangement is advantageous when more than three contacts are disposed in the travel path of the wiper contact actuated by the slide 624, and the selective bridging of any one of a plurality of contacts can be obtained.

With respect to either the illustrated or the alternative arrangement of teeth described, the spring pressed ball and detent at the opposite end of the slide 624 from the cam element 706 is of value in making the neutral position of the slide 624 somewhat more stable than any of the other stable positions afforded the slide 624 in that greater pressure upon the slide 624 must be employed to displace the slide 624 from its neutral position than from any of the other stable positions thereof, thus enabling the user to ascertain the location of the slide 624 by means of touch or finger pressure, rather than having to resort to visual ascertainment. It will be appreciated with either of the constructions described above that in order to minimize wear and tear

it is generally desirable to employ a plurality of teeth 702 as well as a plurality of teeth on the cam element 706, with the number usually being limited solely by the space limitations.

It will be noted that the exposed external configuration of the slide 624 corresponds to the adjacent contours of the sheath 500 and amounts to a continuation thereof when the slide 624 is in its neutral position, and it also being noted that when the slide 624 is in either of its limiting positions which involves a displacement preferably on the order of about 0.050 to 1/16 of an inch, the lateral edges of the slide 624 constitute a slight discontinuity with adjacent surfaces of the sheath 500; such discontinuity or slight lateral projection of an edge of the slide 624 being perceptible to the finger touch of an operator grasping the steering wheel and apprising him of the position of the slide 624. In order to facilitate recognition by the operator that his fingers are in contact with the slide 624, which fact might be relatively difficult to ascertain when the slide 624 is in its neutral position and has its peripheral edges essentially merging smoothly with contiguous surfaces of the steering wheel rim sheath 500, it is preferred that the external surface of the slide 624 be roughened, knurled or provided with a check pattern such as customarily provided on wooden gun stocks and the like, such pattern of roughening of the external surface of the slide 624 being indicated at 630.

An appreciation of the switching functions accomplished by manipulation of the switch means 52 by appropriate manipulation of the slide button 200, the push button 274 and the slide 624 will be best appreciated upon reference to the composite FIGS. 34 through 37, inclusive. Such composite figures illustrate various positions assumed by the wiper contacts 182 and 260 and of the contacts 304 and 306 upon such manipulation. Specifically, in the composite FIG. 34, FIG. 34a illustrates the slide 200 in its intermediate or neutral position and shows the push button 274 in its extended neutral position. FIG. 34b shows the positions of the wiper contacts 182 and 260 in relation to the contacts 176, 178 and 162 corresponding to FIG. 34a, and in addition FIGS. 34b and 34c show the positions occupied by the contacts 306 and 304 in relation to the contact 162 when the slide 624 as exemplified by the member 340 attached thereto is in its neutral position. Accordingly, the composite FIG. 34 shows a condition of contacting elements of the switch means 52 in a position such that the lead 44 (see FIG. 2) is not connected to any of the contacts 62, 64, 66 and 68.

FIG. 35a of the composite FIG. 35 shows the slide 200 and the push button 274 both moved from the positions thereof shown in 34a, that is, the slide button 200 has been moved to one of its extremes of movement and in addition the push button 274 is depressed, the neutral positions of such elements being shown in dashed outline. Such movement of the slide 200 results in a movement of the wiper contact 182 into a position such as to bridge the contacts 160 and 178, such direction of movement of the wiper contact 182 being indicated by the arrow 760, the neutral position of the wiper contact 182 being shown in dashed outline. Further reference to FIG. 35b shows that the wiper contact 260 is moved by the push button 274 to a position intermediate but not in contact with the contacts 306 and 304, as the latter contacts remain in their normal posi-

tions by virtue of the slide 624 and the element 340 remaining in their neutral or intermediate positions.

FIG. 36 shows the slide button 200 moved to its opposite extreme of movement from that shown in 35a and FIG. 36a also shows the push button 274 depressed from its normal position, the normal positions of the slide and push buttons 200 and 274 being indicated in dashed outline. Such movement of the slide and push buttons 200 and 274 result in the wiper contact 182 bridging the contacts 160 and 176, the normal position and direction of movement of the wiper contact 182 being shown respectively in dashed outline and by an arrow. FIG. 36b shows the push button 274 having moved the wiper contact 260 into such a position that it bridges the contact 162 and the contact 306, this latter condition existing for the reason that the slide 624 has been moved in the direction of the arrow indicated at 770 to engage the contact 306 with the wiper contact 260.

20 The composite FIG. 37 indicates the slide button 200 in its intermediate or neutral position with the push button 274 being depressed so as to move the wiper contact 260 into a position such as to bridge the terminal 162 to the terminal 304, it being noted that the slide 624 is shown as having been moved from its neutral position in the direction indicated by the arrow 772. It will be further noted on inspection of FIG. 37b that the wiper contact 182 does not engage either of the terminals 178 or 176 and remains in its neutral position corresponding to the neutral position of the slide button 200.

While FIGS. 34 through 37 do not indicate all the possible permutations of positions of the slide button 200, the push button 274 and the slide 624, the illustrations bring out the flexibility in selection of switching conditions accommodated by the switch means 52. It is again to be particularly noted that where the contact 162 is to be electrically connected to either of the contacts 304 or 306 at least two conditions must be met, namely, the push button 274 must be depressed and in addition the slide 624 must be displaced from its neutral position to one of its extreme positions. Accordingly, considerable flexibility is achieved in the making of connection of the contact 162 to the contacts 304 and 306 is achieved. For example, the push button 274 can be depressed and the slide 624 reciprocated between its limiting positions to alternately electrically connect the contact 162 to the contacts 304 and 306, it being noted that such will result in the system shown in FIG. 2 in alternate loud and soft horn signals. Alternatively, the slide 624 can be positioned in either of its limiting positions and the push button 274 depressed at such times as it is desired to actuate a horn for a sound level determined by the selected limiting position of the slide 624. It will also be appreciated that inadvertent movement of the slide 624 to either of its limiting positions will not result in an inadvertent horn actuation as the horn will not be actuated until such time as the push button 274 is depressed.

60 As will be clear to those skilled in the art in the light of the preceding discussion of the switch means 52, the slide 300 can be provided with yet a third contact similar to and interposed between the contacts 304 and 306 in the event it should be desirable that switching connection be made for any purpose when the slide 624 is in its neutral position and the push button 274 is depressed. Such a modification of the switch means is in-

dicated in the composite FIGS. 38 through 40, wherein an additional contact similar to and interposed between the previously described contacts 304 and 306 is provided, such additional and intermediate contact being designated by the reference numeral 800. The composite FIG. 38 illustrates the slide button 200, the push button 274 and the slide 624 (as represented by the position of the element 340) in their neutral positions, it being noted that in this condition the wiper contact 260 is spaced from the contacts 304, 306 and 800. Movement of the manually actuatable switch controls to be positions corresponding to the previously described composite FIG. 35 results in the wiper contact 182 bridging or electrically connecting the contacts 160 and 178, and in addition results in movement of the wiper contact 260 as indicated by the arrow 802 into a position electrically connecting or bridging the contact 162 to the optional contact 800 provided in this embodiment of the invention, as shown in composite FIG. 39.

Composite FIG. 40 illustrates the slide button 200 moved to one of its limiting positions and the push button 274 being depressed with the slide 624 being moved to one of its limiting positions as indicated by the arrow 810, with the result of the wiper contact 182 bridging the contacts 160 and 176 and the wiper contact 260 bridging the contact 162 to the contact 304, it being noted that the spacing of the contact 800 from the contact 304 is such that the wiper contact 260 does not engage the contact 800. If desired, and as inspection of FIG. 40b will make evident, the extent of the contact 800 in the direction of the spacing of the contacts 304 and 306 can be such that when the contact 260 is in the position shown thereof and the slide 624 is in the position corresponding to the positions of the contacts 304 and 306 that the wiper contact 260 will concurrently engage the contacts 160 electrically with both the contacts 304 and 800.

While the preceding discussion has been directed primarily to the switch means 52 and its mode of mounting and physical incorporation into the steering wheel 102 has been emphasized, it will be understood that such foregoing discussion is equally applicable to the switch means 50 and its structural relation to the steering wheel 102 as in essence the switch means 50 and its structural relationship to the steering wheel constitutes a mere image of the switch means 52 and the latter's structural relationship to the steering wheel 102.

STEERING WHEEL SPOKE MOUNTING OF THE SWITCH MEANS

While steering wheel rim mounting of the previously described switch means 50 and 52 is generally preferred, it is not essential that such switch means be mounted in the steering wheel rim, and alternatively, such switch means may be mounted in the spokes of the steering wheel as may be preferred by some.

Such alternative mounting of the switch means 50 and 52 is illustrated in FIGS. 28 through 33. In such alternative mode of incorporating the switch means 50 and 52 in the steering wheel, the steering wheel is designated generally at 820, and includes a hub 922, spokes 824 and 826, and a rim 828. As in the previously described embodiment, the steering wheel 820 comprises a metallic frame about which is integrally formed or molded a sheath of hard rubber or the like as is conventional. In the practice of the invention according to the instant embodiment, the frame of the

steering wheel 820 is comprised of tubular metallic members 830 and 832 which have their adjacent ends secured to the hub 822 and which have threaded upon their outer extremities hollow casings 834 and 836 respectively. Short elongated members 838 and 840 are threaded into the remote ends of the casings 834 and 836 in alignment with such casings and the tubular members 830 and 832, respectively, such elongated members 838 and 840 being either solid or tubular as shown, whichever may be preferred. The elements 830 through 840 constitute the metallic framework of the spokes 824 and 826 about which the previously mentioned sheath of hard rubber or synthetic resin 842 is formed or molded. A circular ring of solid steel rod 844 is provided to constitute the frame or core of the rim portion 828 of the steering wheel 820, and the remote extremities of the elongated members 838 and 840 are secured by welding or the like to diametrically oppose portions of the annular metallic ring or rod 844. As will be evident to those familiar with details of construction of conventional steering wheels, the sheath 842 is integral and embraces the metallic framework of both the spokes 824 and 826 as well as the metallic frame elements or core of the rim 828.

Generally speaking, the casings 834 and 836 are generally similar to the previously described casings 400 and 420 and are intended for a similar purpose, electric switch means 850 corresponding to previously described switch means 52 being positioned in the casing 836, and electric switch means designated generally at 852 being mounted in the casing 834, it being understood that the switch means 852 corresponds to the previously described switch means 50.

As best shown in FIG. 33, the switch means 850 includes a slide button 854 that corresponds to the previously described slide button 200, a push button 856 that corresponds to the previously described push button 274, and a slide 858 that corresponds to the previously described slide 624. It will be observed upon inspection of FIG. 33 and FIG. 28 that the slide and push buttons 854 and 856 are disposed on the side of the spoke 826 facing toward the operator or manipulator of the steering wheel 820 and that the slide 858 is disposed on the opposite side of the spoke 826. The arrangement is such that the movement of the slide 854 is transverse to the major dimension of the spoke 826, with the movement of the slide 858 being parallel to the direction of movement of the slide button 854. As in the case of the previously described embodiment of the invention, the external exposed surface of the slide 858 smoothly merges with contiguous external surfaces of the sheath 842, and although not so illustrated in this embodiment of the invention, the external surface of the slide 858 can if deemed expedient be roughened or checked as in the case of the slide 624.

Further elaboration upon details of the construction of the switch means 850 and 852 and their style of incorporation in the steering wheel 820 is deemed to be unnecessary in view of the detailed description of the previously described embodiment of the invention.

The steering wheel 820 is provided with a rotary electric connector indicated in dashed outline at 860, whereby the electric switch means 850 and 852 are connected via electric conductors in the tubular members 830 and 832 to other components of the signaling system as will be explained presently. It will be appreciated that the rotary electric connector 860 serves the

same roll for the embodiment shown of the invention in FIGS. 28 through 33 that the rotary electric connector 70 satisfies in the previously described embodiment of the invention and as best shown in FIGS. 4 and 41. Since the rotary electric connectors 70 and 860 are identical, a detailed description of the rotary electric connector 70 will suffice for both.

ROTARY ELECTRIC CONNECTOR

Attention is now directed to FIGS. 41 through 45 for an understanding of the construction of the rotary electric connector 70.

As best shown in FIG. 42, the inverted hub 106 of the steering wheel 102 is non-rotatably secured by means including a nut 866 upon a rotatable tubular steering shaft 868 in a conventional manner. Concentrically disposed about the rotatable steering shaft or tube 868 are spaced inner and outer tubular housings 870 and 872 being fixedly secured to the automobile in a non-rotatable fashion by entirely conventional means, not shown. It will be noted that the upper end portion of the outer tubular housing 872 is radially enlarged and terminates at its upper end in a cylindrical configuration 874 that is received within the annular depending peripheral flange 876 of the hub 106 in spaced relation thereto; this being also in accordance with conventional automobile steering column construction.

As also is clearly shown in FIG. 42, the inner tubular housing 870 terminates at its upper end in an inverted bell shaped configuration including an upwardly divergent section 878 and an uppermost cylindrical section 880.

The rotary electric connector 70 comprises an upper section designated generally at 882 and a lower section designated generally at 884 which are respectively carried by the rotatable steering wheel hub 106 and the non-rotatable cylindrical section 880 of the inner housing 870, respectively, the arrangement being such that the lower section 884 of the connector 70 is non-rotatable and the upper section 882 is rotatable along with the steering wheel 102.

The upper section 882 of the rotary electric connector 70 comprises a concentric series of metallic, electrically conductive cylindrical shells 888, 890, 892, 894, 896, 898, 900, 902 and 904 that are disposed about the steering shaft 868 below the central portion of the hub 106 with the electrically conductive cylindrical shells 888 through 904 being spaced and secured together by annular cylindrical shells of electrically insulative material such as epoxy resin, silicone rubber, neoprene, or nylon, indicated at 906, 908, 910, 912, 914, 916, 918 and 920. The rings 888 through 904 as well as the insulating sleeves 906 through 920 plus the ring 924 are maintained in concentric relationship about a shaft 868 by means of the metallic bushing 922 disposed with a sliding fit about the shaft 868 (such sliding fit of the bushing 922 being for the purpose of facilitating installation of the connector section 882 upon the shaft 868). An insulator sleeve 924 is interposed between and bonded to the bushing 922 and the electric conductor cylindrical shell 888. It will be noted on one hand that the bushing 922 as well as the rings 888 through 904 are cross hatched as metal of the same piece, and the reason for this will become manifest during an ensuing description of a preferred method for fabricating the rotary electric connector 882. For a similar reason it will be noted that the insulator shells

906 through 920 and the insulator 924 are also cross hatched as being of a single piece of plastic. This is because of the preferred method of making the connector 882 that will be subsequently described. The upper end of the outermost cylindrical shell of electrically conductive material is provided with a radially outwardly extending flange 925. A centrally apertured mounting plate 927 is secured to the underside of the central portion of the hub 106 by means of peripherally spaced mounting screws 928. The mounting plate 927 is provided with an integral depending finger 930 adjacent the periphery thereof, such depending finger 930 extending downwardly into the annular space 932 intermediate the inner and outer housings 880 and 874, and the purpose of the depending finger 930 will be presently described. The bonded and substantially integral structure comprised of the electrically conductive cylindrical shells 888 through 904, the insulating cylindrical sleeves or shells 906 through 920, and the insulating sleeve 924 are secured to the hub 106 by means of peripherally spaced screws 934 that extend upwardly through openings 935 provided with electrically insulative bushings 936 in the mounting flange 925, the upper ends of the screws 934 being threaded into the central portion of the hub 106.

As will be noted an apertured disc 938 of resilient and electrically non-conductive material such as foamed, natural or synthetic rubber is interposed between the mounting plate 926 and the upper ends of the cylindrical conductors and insulators, whereafter the resiliency and the thickness of the disc 938 provides a wide adjusting and mating tolerance during final assembly. After appropriate adjustment of the various screws 934 to retain the assembly in position prior to final assembly; these screws allow the assembly to float and adjust as against the disc 938, with the various screws 934 serving as driving dogs, whereby the assembly 882 turns smoothly with the steering wheel when the latter is rotated.

Electrically isolated terminals are provided at the top of the hub 106 that are electrically connected to the various electrically conductive rings 888 through 904. Since each of such terminals are connected in essentially identical fashion, a detailed description of one of such terminal connections will suffice for all of such terminals. Accordingly, the terminal connection for the electrically conductive cylindrical shell 888 comprises aligned openings through the hub 106 and the mounting plate 927 overlying a portion of the cylindrical shell 888 is provided with a flanged electrically insulative bushing 940 which electrically insulates a metallic screw 942 and 926 from the hub 106 and the mounting plate 927, the screw 942 being electrically conductive and extending downwardly through the disc 938 to be threaded into an internally threaded opening 944 in the upper end of the cylindrical shell 888, whereby the screw 942 is electrically connected to the shell 888. While the diameter of the portion of the screw 942 is shown as being less than the wall thickness of the cylindrical shell 888, the diameter of the portion of the screw 942 threaded into the cylindrical shell 888 can be greater than the wall thickness of the cylindrical shell 888 provided such diameter is not sufficiently great that the screw 942 engages either the adjacent cylindrical shell 890 or the bushing 922. This is true for the reason that the various terminals attached or connected to the electrically conductive cylindrical shells

are not in their preferred construction arranged along a radial line, but are rather distributed angularly about the steering shaft 868, as best shown in FIG. 44. Also as shown in FIG. 44, a terminal lug or solder lug 950 is engaged under the head of the screw 942 to which an insulated electric conductor 966 is connected. Accordingly, the insulated electrical conductor 966 is electrically connected to the cylindrical shell 888. In a similar manner and connected to the various other cylindrical electrically conductive shells are provided terminals 954, 956, 958, 959 and 960, which additional terminals being respectively connected to insulated electrical conductors 962, 964, 966, 967 and 968.

Whereas the upper extremities of the concentric conductive cylindrical shells and the intervening cylindrical insulators terminate at their upper extremes in a common plane seated flush against the underside of the disc 938, it is preferred, though not essential, that the electrically conductive cylindrical shells 888 through 904 extend downwardly a short interval below the lower extremities of the insulators as clearly shown in FIG. 42.

To a large extent, the lower section 884 of the rotary electric connector 70 is complementary to the previously described upper section 882, and the same will be seen to comprise in correspondence to the series of electrically conductive shells 888 through 904 a series of concentric electrically conductive shells 970, 972, 974, 976, 978, 980, 982, 984 and 986 separated and bonded in concentric relationship to each other by cylindrical shells of electrically insulative material such as indicated at 988, etc. A bushing 990 is bonded to the innermost electrically conductive shell 970 by an intervening shell of electrically insulative material 992, such bushing 990 receiving the drive shaft 868 therethrough for free rotation. The structure of the lower section 884 thus far described is received within the upper cylindrical portion 880 of the innermost tubular housing 870 and is fixedly retained therein against rotation by means of a rubber sleeve tightly fitted between the tubular section 880 and the outermost electrically conductive shell 986, such rubber sleeve being designated at 994. Accordingly, the lowermost section 884 of the rotary connector 70 is fixed relative to the tubular housing 870 with the drive shaft 868 rotatably extending therethrough.

A collar 996 is fixed to the shaft 868 in a non-rotatable fashion by means of a drift pin 998 extending therethrough, and the radially outwardly extending flange portion 1000 of the collar 996 is provided with a depending finger 1002 for a purpose presently to be described, it being noted that the finger 1002 depends into the annular space between the drive shaft 868 and the upwardly diverging section 878 of the inner tubular housing 870 of which 1206 turn signal mechanism is shown in dashed outline. As those skilled in the art of construction, other means may be provided for securing the collar 996 to the steering shaft 868, by other means such as keying, or splining or by press fitting.

An apertured disc 1004 of electrically insulative material such as inexpensive plastic is rotatably disposed about the shaft 868 to slidably rest upon the upper flat surface of the horizontally extending portion 1000 of the collar 996, whereby the disc 1004 is supported. It will be appreciated that the disc 1004 serves to assure the prevention of or limiting of any downward creeping or movement of the lower section 884 about the shaft

868 in the event that the rubber sleeve 994 fails in this function in any degree.

In the preferred construction the electrically conductive cylindrically shells 970 through 986 extend downwardly a short interval below the lower ends of the insulating shells 988 as shown, and a plurality of insulated electric conductors are electrically connected to the lower ends of the cylindrical shells 970 through 986 as by soldering or the like as clearly shown in FIG. 42 with such electric conductors thence extending as a compact bundle 1006 downwardly through an opening 1008 in the disc 1004 and thence outwardly from the inner housing 870 through an opening 1010 into the annular space 1012 between the tubular housings 870 and 872 as shown in FIG. 42. In this manner, the electrically conductive shells 986, 970, 972, 974 and 976 are respectively connected to insulated electric conductors 1014, 1016, 1018, 1020 and 1022. As will be presently explained, the electrically conductive shells 970 through 986 are electrically connected respectively to the electrically conductive shells 888 through 904 by the rotary connector 70, whereby the electric conductors 1014 through 1022 are respectively connected electrically to the previously described electric conductors 962, 967, 966, 968 and 964 as best seen in FIG. 42 and FIG. 45.

As mentioned previously, means is provided for electrically connecting the cylindrical shells 970 through 986 to the shells 888 through 904 respectively. Since 30 a secondary means is provided for connecting each of such pairs of cylindrical shells, a detailed description of such means provided for electrically connecting the shells 970 and 888 will suffice for all of such means. The means provided for electrically connecting the cylindrical shells 970 and 888 are designated in FIG. 42 generally at 1040, and such means 1040 are shown in enlarged sectional detail in FIG. 43, wherein it will be seen that a cylindrical recess 1042 is provided in the upper end of the shell 970, with the lower end of the cylindrical recess 1042 communicating with a coaxial cylindrical recess 1044 of greatly reduced relative diameter at its lower end. A contactor pin 1046 having an enlarged head 1048 of convex configuration is provided such that the end of the contactor pin 1046 remote from the head 1048 is received within the smaller cylindrical recess 1044. The diameter of the head 1048 is such that the same can be slidably received within the recess 1042 as shown, and the pin 1046 is urged radially outwardly from the recess 1042 by a coiled compression spring 1050 seated between the bottom of the recess 1042 and the head 1048. The contactor pin 1046 including its head 1048 is metallic and electrically conductive and in electrical engagement with the cylindrical shell 970 by means of the metallic and electrically conductive compression spring 1050 as well as by engagement of the pin 1046 with the sides of the small recess 1044. Accordingly, the contactor pin 1046 including the head 1048 thereof is axially movable with respect to the cylindrical shell 970 and is resiliently urged into yielding engagement with the adjacent end of the cylindrical shell 888 for electrical contact with the latter. The resilient mounting of the contactor pin 1046 assures the contactor pin 1046 making continuous and uninterrupted electrical connection between the cylindrical shells 970 and 888 during relative rotation of the upper and lower sections 882 and 884 despite any axial irregularities in the dimensions or in the

event of at least some degree of misalignment of the cylindrical shells 970 and 888.

As clearly shown in FIG. 44, the electrical conductors 967, 962, 964, 966 and 968 extend from their terminal connections with the rotary connector 70 into the tubular member 362, and as best seen in FIG. 42, whereby they may be extended for appropriate connection to terminals and contacts of the electric switch means 52.

Accordingly, as to the switch means 52, the connections of the conductors 967, 962, 964, 966 and 968 can be such that the conductor 966 is connected to the terminal 164 so that the conductor 966 corresponds to the lead shown at 48 in schematic of FIG. 2, and so that the conductor 1016 as best seen in the lower section 884 of FIG. 42, corresponds to the lead indicated at 88 in FIG. 2. Similarly, the conductors 967, 968, 964 and 962 are connected to the terminals or contacts 62, 64, 66 and 68 of the switch means 52 with the conductors 1018, 1020, 1022 and 1014 corresponding to the leads 84, 86, 82, and 80, respectively in the schematic drawing of FIG. 2.

In a similar manner, electric conductors 961, 963, 965, 969 and 971 couple through the conductive shells 896 through 902 and 978 through 984 of the rotary connector 70 to connect to the switch means 50 to correspond to the leads 46, 72, 74, 76 and 78 of the schematic drawing of FIG. 2. As best shown in FIGS. 42 and 44, tab screws 926 and 942 are connected respectively to conductors 965 and 966 from which said screws are communicated to the same conductor shell 888. Obviously to those skilled in the art, it is entirely a matter of choice to whichever ring is used for the hot feeder ring. It will be evident that the connector 70 can be made to include if desired a greater number of pairs of cooperating conductive shells, whereby additional connections therethrough can be made to the switch means 50 and 52 (as when such switch means includes the additional contact shown in the modification of composite FIGS. 38 through 40), as well as to such other switch means, not shown, with which the steering wheel 102 (or 820) may be provided. From the foregoing, the mode of connection of the rotary connector 860 (see FIGS. 28 through 33) to the switch means 850 and 852 will be evident and a detailed description thereof will not be necessary for those skilled in the art.

It is especially important to note that the rotary connector 70 is compatible with the cancelling structure (not shown) of conventional turn signal switch means such as may be initially actuated by a conventional turn indicator control arm indicated in dashed outline at 1060; this being true whether such cancelling means is disposed in the annular space 932 or in the annular space within the divergent portion 878 of the inner housing 870. When the cancelling means is in the last mentioned space and secured to the housing 870, the same can be arranged to coact in the conventional manner with the depending finger 1002, or with the depending finger 930 when disposed in the space 932 and secured to either of the housings 870 and 880; it being noted that such fingers 1002 and 930 rotate with the steering wheel and can on rotation of the wheel in a direction opposite to the sense of turning signal initiated by use of the lever 1060 cause cancellation of the turning signal in the usual way.

Attention shall now be directed to FIG. 44 whereby multiple cam locking slots 973 are conventionally used

to interlock the present used horn rim to the hub 106, and threaded apertures 975 in the hub 106 also are conventional means for securing the conventional horn components to the hub 106.

METHOD OF MAKING COMPONENTS OF THE ROTARY ELECTRIC CONNECTOR

Attention is now directed to FIGS. 46 through 51, inclusive, for an understanding of the preferred method 10 of making the upper and lower sections 882 and 884 of the rotary connector 70. There is initially provided as by molding or any other suitable process a structure such as shown in FIGS. 46 to 49 comprising an integral body of electrically conductive metal such as aluminum 15 corresponding to the bushing 922 and the concentric spaced cylindrical shells 888 through 904, such elements being connected by integral tie bars 1070, 1072, 1074 and 1076. As clearly shown in FIGS. 46 and 49, the cylindrical shell 904 includes the integral flange 20 925.

The structure shown in FIG. 46 is placed on a horizontal mold disc 1080 having crossed grooves 1082 and 1084 which accommodate the tie bars 1070 through 1076 when the structure shown in FIG. 46 is placed on the mold plate or disc 1080 in a position inverted from that shown in FIG. 42. With the structure shown in FIGS. 46 and 49 placed on the mold plate or disc 1080 as described, it will be apparent that the mold plate 1080 closes the ends of the spaces between the bushing 25 and the cylindrical shells at the end at which the tie bars 1070 through 1076 are disposed. With the structure shown in FIGS. 46 and 49 positioned as described on the mold disc or plate 1080, the spaces between the bushing 922 and the cylindrical shells 888 through 904 are filled to the extent shown in FIG. 47 by a moldable synthetic resin such as epoxy to form the previously described insulation sleeves 924 and 906 through 920. The synthetic resin constituting such insulating sleeves can be a thermoplastic resin and be simply melted and poured into the mold defined by the mold plate 1080 and the structure shown in FIG. 46 and allowed to cool, or alternatively, the synthetic resin can be of the thermo-setting type, with the reactants simply being properly blended and poured into the mold while still in a 30 plastic state and allowed to react and harden. For example, a liquid unpolymerized epoxy resin and liquid hardener thereof of conventional character can be mixed and poured into the mold and then allowed to set. In any event, it is preferred that the mold be only filled to such an extent that the insulating sleeves only extend to the end of the bushing 922 indicated at 1086.

After the insulating sleeves 924 and 906 through 920 have been formed in the structure shown in FIGS. 46 and 49 to arrive at the structure shown in FIG. 47, such structure is removed from the mold plate 1080 and chucked in a lathe and the tie bars 1070 through 1076 are machined from the structure to produce the configuration shown in FIG. 48. Preferably, the structure shown in FIG. 48 is also chucked in the lathe and the sleeves 888 through 904 are machined at their ends remote from the position previously occupied by the tie bars so that such sleeves terminate in a common plane 45 normal to the axis of the structure. Openings are then drilled into and tapped into the shells 888 through 904 for accommodating the terminal screws such as the opening indicated at 1090 and best seen in FIG. 48 for accommodating the previously mentioned screw 942.

In addition holes 935 are enlarged by drilling through the aperture mounting flange of the outermost ring 904 and as best seen in the upper section 882 in FIG. 42. The structure shown in FIG. 48 is then ready for assembly with the remaining components of the rotary connector 70 as the upper section 882 shown in FIG. 42.

The lower section 884 of the rotary electric connector 70 is fabricated in substantially the same manner as the previously described preferred method of making the upper section 882, and differs essentially therefrom substantially solely in the fact that the flange 925 is either not initially included in the mold structure or is after the provision of the insulating sleeves machined from the structure along with the tie bars. As in the case of making the upper section 882, after the insulating sleeves have been formed so as to insulate the concentric electrically conductive sleeves and to retain the latter in assembled relation, openings are drilled in the conductive sleeves such as the openings or recesses 1042 and 1044 shown in FIG. 43. Completed in such manner, the structure thus made is ready for assembly in the rotary switch as shown in FIG. 42 as the lower section 884.

An alternative form of rotary connector to be employed in lieu of the rotary connector 70 or 860 is shown in FIGS. 52 through 55 and such alternative form of rotary electric connector is designated generally at 1100, the same comprising an upper section designated generally at 1102 and a lower section designated generally at 1104. The upper section 1102 comprises a cup-shaped member of electrically insulative material such as nylon or plastic that includes a flat lower wall 1106 that is integral with a reentrant tube or bushing structure 1108 with the latter being disposed about the steering wheel shaft 868. The cup-shaped structure of the upper section 1102 also includes an integral outer wall 1110 that is provided with a radially outwardly extending flange 1112. The upper section 1102 of the rotary electric connector 1100 is secured to the central portion 106 of the hub by means of screws 1114 slidably extending through apertures 1116 in the flange 1112 and securely threaded into the hub 106, with coiled compression springs 1118 embracing the screws 1114 and biased between the hub 106 and the flange 1112.

A concentric series of spaced annular conductor elements 1120 through 1136 are attached to the planar underside of the bottom wall 1106, such annular elements being electrically connected to electric conductors such as the insulated electric conductor shown at 1138, the connection being by means of the conductor thereof extending through the wall 1106 through a suitable aperture provided in the latter and soldered to the ring 1120. If desired, such connection can be most conveniently made by providing an aperture entirely through the wall 1106 and the ring 1120 with the bared wire of the insulated conductor 1130 extending entirely through the wall 1106 and the ring 1120 and thereafter soldering the bare wire to the ring 1120 with excess length of the bared wire and solder being ground or cut away from the lower surface of the ring 1120 so that the underside of the ring 1120 remains planar.

The lower section 1104 of the rotary connector 1100 is generally similar to the upper section 1102 and comprises an inverted cup-shaped body of electrically insulative material such as a synthetic resin, and is comprised of an upper wall 1150, an inner wall or bushing

1152, and an outer depending wall or flange 1154, it being noted that the latter depends a greater distance from the wall 1150 than the bushing 1152. The outer wall 1154 is press fitted into the upper end portion 880 of the inner housing 870, and an integral radially extending flange 1156 seats upon the upper end of the inner housing 870 as shown in FIG. 52. As best seen in FIG. 52, the conventionally used ball bearing system is absent in view that power steering mechanisms do not warrant this extra expense; and that the nylon walled bushing 1152 is more than adequate for a non-wearing bearing surface.

A concentric series of electrically conductive rings 1160, 1162, 1164, 1166, 1168, 1170, 1172, 1174 and 1176 are bonded or attached to the upper planar surface of the wall 1150. A plurality of insulated conductors such as that indicated at 1178 have the wires thereof electrically connected to the conductor elements 1160 through 1176 with such electric conductors being grouped or bundled and extending downwardly through an apertured disc 1180 and thence through an opening 1182 in the inner housing 870 from whence bundled or cabled electric conductors can extend down through the steering column for connection to the electric system previously described in connection with FIG. 2. The disc 1180 underlies the lower edge of the bushing 1152 and has its peripheral edge seated in an annular groove 1184 in the wall 1154.

A collar 1200 is fixed to the steering shaft 868 by means of a drift pin or rivet 1202, and such collar is provided with a depending finger 1204 for coaction with the cancelling mechanism indicated in dashed outline at 1206 of a conventional turn signal indicator that is actuated by a control lever shown in dashed outline at 1208. It will be noted that the cancelling system 1206 is disposed within the inner housing 870 and is rigidly secured thereto so as to be actuated by the finger 1204 on appropriate turning movement of the steering wheel 102.

Means is provided to assure continuous electrical contact between the generally annular conductor elements 1160 through 1176 with the annular conductors 1120 through 1136, respectively, during relative turning movements of the upper to the lower sections 1102 and 1104 of the rotary electric connector 1100. Such means is best shown in FIGS. 53 through 55 in connection with the conductor 1176, it being understood that all of the conductors 1160 through 1176 have similar provision. Except for a gap indicated at 1220, the generally annular conductor 1176 is continuous throughout its circumferential extent. The generally annular conductor 1176, which is formed of a resilient metal, such as copper beryllium alloy, is detached from the wall 1150 at one side of the gap 1220 as indicated at 1222, and is given a convex upper curvature as indicated at 1224 during the short angular interval through which the generally annular conductor 1176 is separated from the wall 1150.

The detached portion 1222 of the conductor 1176 may be smoothly curved or may simply have a substantially flattened V-shaped configuration to present the upwardly facing convex surface 1224 shown in FIGS. 54 and 55. In any event the detached portion 1222 can by virtue of the resiliency or spring-like character of the material of the substantially annular conductor 1176 flex toward the wall 1150 with such freedom to yieldingly flex being enhanced by the spacing of the gap

1220, it being noted that such gap tends to close on the portion 1222 being flexed toward the wall 1150.

The arrangement is such that the apex or part 1226 of the portion 1222 spaced the most from the wall 1150 yieldingly bears or is given a spring-like bias against the conductor ring 1136 when the upper and lower sections 1102 and 1104 of the connector are brought into assembled close proximity of each other. Such electrically conductive sliding contact of the portion 1222 of the conductor 1176 with the conductor ring 1136 assures continuous contact between the conductors 1176 and 1136 during rotation of the latter (with the steering wheel) relative to the stationary conductor 1176, despite minor irregularities that might occur in alignment or in the planar surface of the conductor 1136 due to either faulty manufacture or wear of the latter. Thus electrical continuity is maintained between insulated conductors 1228 and 1230 connected as shown respectively to the conductors 1134 and 1174.

It will be understood, of course, that each of the substantially annular conductors 1160 through 1176 are provided with gaps and outwardly bowed resiliently portions such as shown in FIGS. 53, 54 and 55 in connection with the conductor 1176, whereby the conductors 1160 through 1174 are respectively in continuous, and biased sliding electrical engagement with the conductors 1120 through 1136 throughout relative rotational movements of the upper section 1102.

The manner in which the connector 1100 can be substituted for the connector 70 in either of the steering wheel embodiments of the invention will be amply evident to those familiar with the art.

Note: In connection with the upper portion of FIG. 52, the upper section 1102 is cup-shaped so as to define by the walls 1106 and 1110 an annular space or wall within which storage is provided for electric conductors, and it being noted that during the assembly of the rotary connector with the steering wheel that it is convenient if not necessary to have slack length in such conductors and the well 1177 provides ample space within which such excess length of the electric conductors can be tucked away. A similar storage area 1178 is provided in section 1104.

The preferred method of making the upper and lower sections 1102 and 1104 of the connector 1100 is simple in execution and as in the case of the connector 70 especially well suited to mass or assembly line production procedures. Such method in the case of the upper section 1102 comprises molding the integral resin body shown in FIG. 56 by conventional techniques, such body including the bushing 1108, the wall 1106, the wall 1110 and the apertured mounting flange 1112.

An annular plate 1250 of copper or etchable electrically conductive material is bonded or fixedly secured by an adhesive to the outer face of the wall 1106 for the making of the conductor rings 1120 through 1136. The exposed face of the plate 1250 is masked so as to leave exposed for subsequent chemical etching only such portions of the plate that lie intermediate the conductor rings 1120 through 1136. In other words, the areas and only the areas of the plate 1250 to constitute the rings 1120 through 1136 are coated with a masking material such as to protect such areas against chemical etching during an ensuing etching operation. Such masking material can, for example, be a wax printed from a stamp upon the surface of the plate 1250, or the outer surface of the plate 1250 can be processed by any

well known and conventional manner such as is commonly employed in the art of making what are known as printed circuit boards by procedures that involve in effect masking areas of metal to be preserved during etching and leaving areas to be removed free of masking material or coated only with a material of ineffective resistance to chemical etching solutions.

After the exposed surface of the plate 1250 has been masked as outlined above, the plate 1250 is etched by 10 a suitable etching solution (for example, when the plate 1250 is copper) to remove all parts thereof that were not masked so that only the electrically isolated conductor rings 1120 through 1136 remain. Openings are then drilled through the wall 1106 so that the electric 15 conductors can extend through the wall and be soldered to the conductor rings in the manner described previously. This completes the upper section 1102 as seen in FIG. 52.

The lower section 1104 is made by a procedure that 20 generally parallels the making of the upper section 1102. A body of synthetic resin is provided by conventional molding techniques to include the bushing 1152, the wall 1150, the flange 1156, and the wall 1154, and which the groove 1184 is formed by either machining 25 or molding as seen in FIGS. 52 and 55.

An annular plate 1290 of resilient, electrically conductive material (such as beryllium-copper alloy) is bonded or secured to the outer face of the wall 1150 by a suitable adhesive, and a series of electrically isolated annular rings is formed therefrom by masking and etching procedures such as in the case of the making of the rings 1120 through 1136. Each of the rings so formed is radially severed at one position about its circumferential extent. Such severing can be by way of cutting (such as by the use of a chisel), sawing or any conventional mechanical means; or alternatively such severing can be by chemical etching accomplished at the same time that material between the rings is etched away in which event an appropriate radial break is 30 made in the circumferential continuity of the material masking each ring or area to be protected against chemical attack. Such break can be by appropriately masking the plate initially, or by masking initially to form complete rings of masking material and then physically removing (as by scraping away) the masking material to make the break. Subsequent etching with such break serves to sever the ring and to define the 35 basis for a gap in the ring such as that shown at 1220 in FIGS. 55 and 61. Subsequent to the etching operation, the ring is separated from the wall for a short interval from one side of the position of severance and physically bent to have a convex surface facing outwardly from the wall 1150 such as shown at 1224 in FIG. 55. The separation can be made by the use of a thin cutting tool, not shown, inserted between the ring 40 and the wall 1150 to break the bond therebetween.

ALTERNATE SLIDE POSITIONING MEANS

Attention is now directed to a plurality of different constructions that can be used in lieu of the teeth 702 and the toothed cam element 702 (see FIGS. 6 and 17).

One of such alternative constructions for use in positioning or controlling the positions of two relatively movable members is shown in FIGS. 67, 68 and 69, wherein the element 1500 is substituted in lieu of the previously described and spring biased toothed cam element 706 as will be understood, and the element 1504

corresponds to the previously described element 700 provided with the dimples or teeth 702 as will be understood. As in the case of the element 706, the element 1500 is provided with teeth 1502 that are lesser in number than teeth 1506 in the element 1504. FIG. 67 shows the element 1500 in a neutral or intermediate central position with respect to the element 1504, and the element 1500 can be shifted laterally to the left or right as shown by the arrows 1508 and 1510 in FIGS. 68 and 69, respectively, so that the registry or the teeth of such elements is shifted either one position to the left or to the right. During such lateral movement in either of such directions the element 1500 by virtue of the resilient means biasing the same toward the element 1504 is cammed toward and tends to resume its initial neutral position until such time as the teeth of such elements have passed a position of direct opposition, and thereafter the camming action reverses in direction and the element 1500 is cammed by virtue of the coaction of the teeth under the urging of the spring means (such as the spring 712 shown in FIG. 6) to one of the limiting positions shown in FIGS. 68 and 69. Obviously, the member 1500 after having reached one of the limiting positions of FIGS. 68 and 69 must be positively pushed laterally in order for the element 1500 to be returned to the position shown thereof in FIG. 67.

FIGS. 70, 71 and 72 illustrate yet another modification that is generally quite similar to the structure shown in FIGS. 6 and 17. This embodiment of the invention includes an element 1512 that corresponds to the previously described element 706, and the same includes teeth 1514. An element 1516 corresponding to the previously described element 700 has a plurality of blunt teeth 1518 corresponding in number to the teeth 1514, and in addition the element 1516 is provided with sharp teeth 1520 and 1522 at the opposite sides of the blunt teeth 1518. FIG. 70 shows the element 1512 in its neutral or central intermediate position with respect to the element 1516, and may be readily moved to either one of its limiting positions shown in FIGS. 71 and 72 by appropriately applying lateral forces to the element 1512 in the directions indicated by the arrows 1524 shown in FIGS. 71 and 72. The action of this embodiment of the invention differs somewhat from that shown in FIGS. 67 through 69 in that the element 1512 can be caused to move from its neutral position with relatively little lateral force and after a short movement in the desired direction will thereafter be cammed with a snap action to its limiting position, it being understood that the element 1512 is resiliently biased toward the element 1516. In the preferred construction, the teeth 1520 and 1522 are of sufficient height as to prevent the element 1512 being displaced laterally beyond the desired limits of its movement.

Still another embodiment is shown in FIGS. 73, 74 and 75, this embodiment of the invention involving the provision of an element 1526 to correspond to the spring biased element 706, the element 1526 being provided with a single sharp tooth 1528. An element 1530 is provided to correspond to the previously described element 700, and the same is stamped to provide a single blunt tooth 1532, such blunt tooth 1532 being centrally grooved or recessed in the blunt face 1534 thereof at 1536 to receive the sharp end or edge of the tooth 1528. The operation of this embodiment of the invention is generally similar to that of the embodiment of the invention shown in FIGS. 70 through 72, except

for the fact that initial movement of the element 1526 in the directions 1538 and 1540 indicated by arrows in FIGS. 74 and 75 is resisted to a slight degree by the necessity for unseating the sharp edge of the tooth 1528 from the groove or notch 1536. As soon as the sharp edge of the tooth 1528 has been unseated from the groove 1536, the element 1526 can be easily moved across the remaining portion of the flat area 1534 and the element 1526 finally cammed by a snap action into the limiting positions shown in FIGS. 74 and 75.

A final modification is shown in FIGS. 76, 77 and 78, this modification comprising an element 1542 corresponding to the previously described element 706, the same having a single sharp tooth 1544. An element 1546 is provided that corresponds to the previously described element 700, and the element 1546 has a single blunt tooth 1548 against which the tooth 1544 is seated when the spring biased element 1542 is in its neutral or intermediate position with respect to the element 1546. It will be appreciated that the element 1544 can be moved in either of the directions indicated by the arrows 1545 and 1548 to seat the element 1542 at its limiting positions much in the same manner as in the operation of the embodiment of the invention shown in FIGS. 70 through 72.

Each of the embodiments of the invention disclosed in FIGS. 67 through 78 afford the noteworthy advantage that precise control of the position of two relatively movable elements can be effected even when the amount of relative movement between such elements is very small. Such constructions are of very great value when space requirements permit only very slight relative movements between two elements or when it is otherwise desired that the degree of relative movement be very limited, while yet preserving a positive degree of control over the relative positioning of such elements. Additionally, the provision of structures such as shown in the various modifications discussed above affords the advantage of the elements being rather positively retained in either of their relatively limiting positions, and also in the fact that the snap actions afforded enable the relative movements and positions to be sensed upon manual actuation of such movements.

Each and every aspect of the illustrated embodiments of the invention have been described in elaborate detail in order to assure a full and complete understanding thereof by those skilled in the art, and any narrowness in scope of the inventive concepts involved is not to be implied therefrom.

It will be amply apparent that each and every illustrated and described embodiment of the invention is susceptible to numerous variations in detail without departing from the spirit of the invention, and accordingly, attention is directed to the appended claims in order to ascertain the actual scope of the invention.

I claim:

- An electric connector comprising first and second sections each of generally cylindrical configuration, each of said sections comprising a radial series of concentric cylindrical shells of alternately electrically conductive and insulative material, said shells being in axial alignment with electrically conductive shells of the sections being in alignment, means for mounting one of said sections for axial rotation relative to the other of said sections, each of the electrically conductive shells of the first section being provided at the end of the latter adjacent to the second section with axially

extensible and movable wiper contacts in axially abutting and sliding engagement with the adjacent axial extremities of the electrically conductive shells of the second section, with spring means biasing each of said wiper contacts axially toward said abutting and sliding engagement, and means at the remote ends of said sections for connecting electric conductors to the electrically conductive shells.

2. The combination of claim 1, including means for mounting said sections for relative axial movement toward and away from each other, and means for yielding urging relative axial movement of said sections toward each other.

3. The combination of claim 1, wherein the provision of an electrically conductive shell with the wiper contact comprises said electrically conductive shell having an axially extending recess therein that opens toward the second section, and said wiper contact comprising a contactor pin having an enlarged head slidably received within the recess with the headed end thereof being disposed toward the second section, and said spring means comprising a coiled compression disposed in the recess and embracing the pin with one end of said spring being seated against the headed end of the pin.

4. The combination of claim 3, wherein the entire axial extent of the pin including the headed end thereof is receivable within the recess, said pin at its axial end remote from the headed end thereof having a transverse cylindrical configuration of lesser diameter than the thickness of said electrically conductive shell, and said recess at its end remote from said other section having a transverse configuration complementary to and slidably receiving the end of the pin remote from its headed end, and said pin and said spring being electrically conductive.

5. The combination of claim 3, wherein the headed end of the pin is convex toward the second section, whereby the headed end of the pin can concurrently contact said electrically conductive shell and one of the electrically conductive shells of said second section without preventing direct sliding electrical engagement of such shells with each other.

6. The combination of claim 2, wherein the provision of an electrically conductive shell with the wiper contact comprises said electrically conductive shell having an axially extending recess therein that opens toward the second section, and said wiper contact comprising a contactor pin having an enlarged head slidably received within the recess with the headed end thereof being disposed toward the second section, and said spring means comprising a coiled compression spring disposed in the recess and embracing the pin with one end of said spring being seated against the head end of the pin.

7. The combination of claim 2, wherein the provision of an electrically conductive shell with the wiper contact comprises said electrically conductive shell having an axially extending recess therein that opens toward the second section, and said wiper contact comprising a contactor pin having an enlarged head slidably received within the recess with the headed end thereof being disposed toward the second section, said spring means comprising a coiled compression spring disposed in the recess and embracing the pin with one end of said spring being seated against the headed end of the pin, said pin, including the headed end thereof, hav-

ing an axial extent that is receivable in its entirety within the recess, said pin at its axial end remote from the headed end thereof having a transverse cylindrical configuration of lesser diameter than the thickness of said electrically conductive shell, and said recess at its end remote from said other section having a transverse configuration complementary to and slidably receiving the end of the pin remote from its headed end, said pin and said spring being electrically conductive, and wherein the headed end of the pin is convex toward the second section, whereby the headed end of the pin can concurrently contact said electrically conductive shell and one of the electrically conductive shells of said second section without preventing direct sliding electrical engagement of such shells with each other.

8. In steering wheel construction of the type wherein a steering wheel is fixed on one end of a rotatable steering shaft that rotatably extends through a fixed tubular steering column, the improvement comprising a rotary electric connector having relatively movable and cooperating upper and lower annular sections respectively mounted on and in the steering wheel and the column, each of said sections being of a generally cylindrical configuration and comprising a radial series of concentric cylindrical shells of alternately electrically conductive and insulative material, with each of said shells having contact solely with the other of said shells that are serially immediately adjacent thereto, said sections being in axial alignment with electrically conductive shells of the sections being in alignment and in relative rotary sliding engagement with each other, said upper section being mounted on the steering wheel for axial movement toward and away from the lower section, resilient means yieldingly urging the upper section into axial engagement with the lower section, and means at the remote axial ends of the sections for connecting electric conductors to the electrically conductive shells, whereby electric circuits can have portions thereof respectively fixed with respect to the fixed steering column and the relatively rotatable steering wheel.

9. In steering wheel construction of the type wherein a steering wheel is fixed on one end of a rotatable steering shaft that rotatably extends through a fixed tubular steering column, the improvement comprising a rotary electric connector having relatively movable and cooperating upper and lower annular sections respectively mounted on and in the steering wheel and the column, each of said sections being of a generally cylindrical configuration and comprising a radial series of concentric cylindrical shells of alternately electrically conductive and insulative material, said sections being in axial alignment with electrically conductive shells of the sections being in alignment and in relative rotary sliding engagement with each other, each of the electrically conductive shells of one of the sections being provided at the end thereof adjacent the other section with an axially extensible wiper contact in axially abutting and sliding engagement with the adjacent axial extremity of the aligned electrically conductive shell of the other section, and spring means recessed in said one section biasing the axial extension of each wiper contact, and means at the remote axial ends of the sections for connecting electric conductors to the electrically conductive shells, whereby electric circuits can have portions thereof respectively fixed with respect to the fixed

steering column and the relatively rotatable steering wheel.

10. In steering wheel construction of the type wherein a steering wheel is fixed on one end of a rotatable steering shaft that rotatably extends through a fixed tubular steering column, the improvement comprising a rotary electric connector having relatively movable and cooperating upper and lower annular sections respectively mounted on and in the steering wheel and the column, each of said sections being of a generally cylindrical configuration and comprising a radial series of concentric cylindrical shells of alternately electrically conductive and insulative material, said sections being in axial alignment with electrically conductive shells of the sections being in alignment and in relative rotary sliding engagement with each other, said upper section being mounted on the steering wheel for

axial movement toward and away from the lower section, resilient means yieldingly urging the upper section into engagement with the lower section, each of the electrically conductive shells of one of the sections being provided at the end thereof adjacent the other section with an axially extensible wiper contact in axially abutting and sliding engagement with the adjacent axial extremity of the aligned electrically conductive shell of the other section, and spring means biasing the axial extension of each wiper contact, and means at the remote axial ends of the sections for connecting electric conductors to the electrically conductive shells, whereby electric circuits can have portions thereof respectively fixed with respect to the fixed steering column and the relatively rotatable steering wheel.
